UNITED STATES PATENT OFFICE.

KENNETH E. STUART, OF PHILADELPHIA, PENNSYLVANIA.

ELECTRIC-RAILWAY SYSTEM.

1,240,897.

Specification of Letters Patent. Patented Sept. 25, 1917.

Application filed April 29, 1912, Serial No. 693,973. Renewed July 17, 1915. Serial No. 40,526.

To all whom it may concern:

Be it known that I, KENNETH E. STUART, a citizen of the United States, residing in the city of Philadelphia, county of Philadelphia, and State of Pennsylvania, have invented a new and useful Electric-Railway System, of which the following is a specification.

My invention relates to an electric railway system suitable for the underground despatch of mail, parcels, etc., in which the traveling cars carry no motormen. My invention relates more particularly to the method of and apparatus for controlling the cars at a distance by the use of preferably shunt wound electric motors, the fields of which are excited from a separate conductor rail extending along the trackway, by which means the cars can be started, stopped or reversed.

My invention relates further to a method of operating a block system to prevent collision between trains, and more particularly by means of the current supplied through the separate conductor rail above mentioned to the fields of the motors.

My invention also resides in a method of and apparatus for indicating automatically in each station whether a particular approaching car or train is to be stopped at the station in question or to pass by without stopping.

My invention further resides in a method of and apparatus for equalizing the braking effect upon empty and loaded cars so that they come to rest within substantially the same distance.

Another feature of my invention is the interlocking of the controllers in a station so that certain mischances are thereby rendered impossible.

My invention further consists in the construction of relays and contactors hereinafter described.

My invention resides in other features hereinafter described and claimed.

For an illustration of one of the forms of my invention reference is had to the accompanying drawings, in which:—

Figure 1 is a diagram of the connections upon a car and between the car and the track and conductor rails and one type of

controller, which is shown in the "reversing position" or position in which it makes such connections as will cause the car to start 55 backward.

Fig. 2 is a diagram of the same connections excepting that the controller is shown in the "braking position" or position in which it makes such connections as will 60 cause the car to be electro-dynamically braked.

Fig. 3 is a diagram of the same connections excepting that the controller is shown in the "starting position" or position in 65 which it makes such connections as will cause the car to start forward.

Fig. 4 is a diagram of the same connections excepting that the controller is shown in the "through position" or position in 70 which it makes such connections as will cause the car to continue at a predetermined speed.

Fig. 5 is a diagram of the electrical apparatus and connections at a terminal station. 75

Fig. 6 is a similar diagram (shown in three portions) for the first block section, supposed to adjoin the preceding section on the right.

Fig. 7 is a similar diagram for the second 80 block section, supposed to adjoin the preceding section on the right.

Fig. 8 is a similar diagram for the third block section, which includes an intermediate station and is supposed to adjoin the 85 preceding section on the right. This figure also shows diagrammatically the electrical apparatus and connections at the said intermediate station.

Figs. 9 and 10 are similar diagrams for 90 portions of the fourth and fifth block sections respectively; each supposed to adjoin the preceding section on the right.

Fig. 11 is a diagram of the connections made by the contactors of the first block 95 section when they are in the "braking position" or position which causes the train to come to rest upon this section.

Fig. 12 is a diagram of the connections made by the same contactors when they are 100 in the "starting position" or position to restart the train after it has been brought to rest upon this section.

Fig. 13 is a diagram of the connections

made by the same contactors when they are in the "through position," or normal position, which in this case are such as to retard the train to a speed at which it can safely 5 enter upon the curved portion of the line.

Fig. 14 is a diagram of the connections made by the contactors of the second block section when they are in the braking position.

10 Fig. 15 is a diagram of the connections made by the same contactors when they are in the starting position.

Fig. 16 is a diagram of the connections made by the same contactors when they are 15 in the through or normal position, which in this case are such as to accelerate the train again to full speed and then pass it over the remainder of the section at substantially that speed.

20 Figs. 17, 18 and 19 are diagrams of the connections made by the contactors of the third block section when they are in the braking, starting and through positions respectively.

25 Fig. 20 is a diagram of the connections made within the controller of the "braking section" of the terminal station when it is in the braking position.

Fig. 21 is a diagram of the connections 30 made within the same controller when it is in the starting position.

Figs. 22, 23, 24 and 25 are diagrams of the connections made within the controller for the "approach section" of either station 35 when it is in the reversing, braking, through and starting positions respectively.

Figs. 26, 27, 28 and 29 are diagrams of the connections made within the controller for the "unloading section," "loading section" or "siding section" of either station 40 when it is in the reversing, braking, neutral and starting positions respectively.

Figs. 30 and 31 are diagrams of the connections made within the controller for the 45 braking section of the intermediate station when it is in the braking and starting positions respectively.

Fig. 32 is a diagram of the connections made within the controller for the switch 50 points of the intermediate station when it is in the "station position," or position in which the switch points are set to direct a car into the station.

Fig. 33 is a diagram of the connections 55 made within the same controller when it is in the "past position" or position to direct a car past the station.

Fig. 34 is a side elevation, partly in section on the line 1—1 of Fig. 35, of one of the 60 contactors above mentioned.

Fig. 35 is a plan view of the same, part being shown with the cover broken away.

Fig. 36 is an end elevation of the same, the left half being in section on the line 2—2 65 and the right half on the line 7—7 of Fig. 34.

Fig. 37 is a sectional end elevation of the same, on the line 8—8 of Fig. 34.

Fig. 38 is a horizontal section, some parts in plan, on the line 3—3 of Fig. 39, of a single ended relay.

Fig. 39 is a plan view of the same.

Fig. 40 is a section on the line 5—5 of Fig. 38.

Fig. 41 is an end elevation, partly in section, on the line 6—6 of Fig. 38.

Figs. 42 and 43 are side elevation, partly in section, and plan view, respectively, of a modified form of relay.

Fig. 44 is a plan view of the pneumatic mechanism for operating the rail switch 80 points from a distance.

Fig. 45 is an end elevation of the same.

Fig. 46 is a front elevation of the frame of the "control table" for the intermediate station, and the system of interlocking to 85 prevent certain mishances, the frame partly broken away.

Fig. 47 is an end elevation of the same, partly broken away.

Fig. 48 is an elevational view of the same 90 from the opposite end, partly broken away.

Fig. 49 is a sectional elevation of the same taken centrally.

Fig. 50 is a plan view of the same, partly broken away.

Fig. 51 is a diagrammatic view of the cams by which the controller interlocking is secured.

Fig. 52 is a side elevational view of the mechanism carried by the car by means of 100 which when approaching the station for which it is intended it automatically indicates the fact that it is intended for that station to the operator there.

Fig. 53 is an end elevation of the same.

Fig. 54 is an end elevation of the same from the opposite end.

Fig. 55 is a plan view of the same.

Fig. 56 is an end elevation of the stationary devices coöoperating with the same.

Fig. 57 is a side elevation of the said stationary devices.

Fig. 58 is a diagram showing the curves of retardation from full speed to rest of an empty car and a loaded car when my system of equalizing the braking effect upon the two is employed.

Referring now to Figs. 1, 2, 3 and 4, T_1 and T_2 are contact conductor rails for the motor field and armature respectively, extending along the trackway and insulated from the ground and from the track rails T_3 , T_4 . M is the electric motor driving the car through the gears G_1 and G_2 and wheels W_1 . S_1 and S_2 are collector shoes carried by the car and bearing upon the conductor rails T_1 and T_2 respectively. The electrical connections upon the car are from T_1 through the shunt field F_1 and the point 125 19 to the frame of the car F and thence through 130

the wheels to and through the track rails T_3 . There is also a connection from T_2 through the differential series field F_2 and the brush B_4 , to the motor armature A_1 and thence 5 through the brush B_3 , point 19, car frame F and wheels to the track T_3 .

There are thus three connections to the motor, *i. e.*, one to the shunt field, one to the armature, and a return connection common 10 to both field and armature. These are used to start, stop and reverse the car in the following manner:

Upon certain sections of the line, which will be clearly indicated hereinafter, the conductor rails T_1 and T_2 , as well as both the track rails T_3 , are insulated from the similar rails of the adjoining sections of the line and connected to a manually operated controller not upon the car. Upon such portions of the 20 line the car may therefore be controlled by an operator at a distance. The manner of doing this is illustrated in Figs. 1, 2, 3 and 4.

The controller used is merely an adaptation of a well-known commercial type having fingers bearing upon a common drum which in various positions makes various connections between them. In this case there are eight fingers and four positions of the drum. The fingers are numbered 11 to 25 18 inclusively and the connections established between them by the drum in each of its several positions are indicated by the lines joining them and passing to the right of them.

Referring to Fig. 3, it will be seen that 35 there is a connection from the positive main to the finger 12 and thence through the drum to the finger 11, which is connected to the conductor rail T_1 , which, it will be remembered, has a connection through the collector shoe S_1 to the shunt field of the motor M on the car. The finger 13 has a connection through the rheostat or resistance R_1 with the positive main and through the 40 drum to the finger 15, which in turn is connected to the conductor rail T_2 , whence the connection is through the collector shoe S_2 to the armature of the motor M through series field winding F_2 . The finger 16 is connected to the track rails T_3 and also through the drum to the finger 17, which is connected to the negative main. As already explained, both the armature and shunt field have a return connection to the track rails T_3 . With 45 55 the connections as shown in Fig. 3, therefore, the motor field F_1 will be excited to full strength while the armature will receive current at a reduced voltage, which may be made suitable for starting the car from rest, and the series field F_2 is in opposition to shunt field F_1 , but the current flow through F_2 is not great, due to resistance R_1 , and therefore the motor field is not greatly weakened by F_2 . As the car is intended to 60 65 move at slow speed only while under the

control of these controllers, it is not necessary to provide another position in which the rheostat R_1 is cut out. Under certain circumstances to be explained later, however, it may be desired to keep the car moving 70 uniformly at the reduced speed with which it arrives upon the portion of the line in question, and for this purpose another position of the controller is provided as shown in Fig. 4. In this position the connections 75 are the same as before excepting that the finger 15 which supplies the motor armature is now connected through the drum to the finger 14 which receives current through a greater resistance than the finger 13. 80

The connections for braking the car are shown in Fig. 2. In this case the motor field F_1 is excited to full strength as before, while the armature instead of being connected to the positive main is connected 85 through the drum and finger 16 to the track rails T_3 , thus completing a short circuit through the armature. Any rotation of the armature will now cause it to generate an electromotive force which on account of the 90 low resistance of the armature circuit will cause a heavy current to flow which in turn resists the rotation of the armature, or in other words exerts a braking effect on the car. This armature current is in reverse direction, and, passing through series field F_2 , causes the latter to act cumulatively with the shunt field F_1 , to produce a still stronger field. As will be shown later, by interposing 95 a suitable resistance in the armature circuit (not shown in Fig. 2) I regulate the braking effect so as not to damage the motor or cause the car wheels W_1 to skid on the rails T_3 .

The method of reversing the direction of 100 the car is shown in Fig. 1. In this case it will be seen that the motor armature is connected through the drum to the finger 12, which receives the full voltage from the positive main. The return connection from the 105 track rails T_3 is, however, no longer directly to the negative main but is through the drum and finger 18 to the negative main through the rheostat R_2 . The field connection from the conductor rail T_1 has also been transferred through the drum and finger 17 to the negative main direct. With these connections it will be seen that the shunt field is now connected in series with the armature, but in shunt or parallel with the rheostat R_2 . 110 Thus, the current now flows from the finger 15 through the conductor rail T_2 , the differential series field F_2 and the armature to the point 19, where it divides, part returning 115 through the fingers 16 and 18 and the rheostat R_2 to the negative main, while a part flows through the shunt field and fingers 11 and 17 to the negative main direct. As the resistance of R_2 is very great compared with 120 that of the remainder of the armature cir- 125 130

cuit, the fall of potential through it at the instant of switching on the current with the motor at rest will be very nearly the full voltage of the power supply. In other words 5 the shunt field will receive very nearly the full voltage of the mains across its terminals and will be excited to a corresponding degree. It will be noticed, moreover, that the direction of the current in the shunt 10 field has been reversed, and is now the same as that of the series field, making a compound field. Without the latter, the motor would now develop a torque in the reverse direction approximating its normal starting 15 torque. By means of the cumulative series starting turns the field is further strengthened and the torque developed in the reverse direction can be made to equal or exceed the normal direction starting torque.

20 It will be noted that the series turns are not essential to this method of reversing, but are useful. They are likewise useful in the operation of braking, since in this case the current in the armature is reversed 25 and the series turns are cumulative with the shunt turns, as above described. It may also be mentioned that the differential series turns improve the constant speed characteristics of the motor in normal ahead running and if properly proportioned are therefore an advantage from every point of view. As the motor gathers speed when so reversed the current and consequently the fall of potential through the rheostat R_2 will diminish. 30 This will weaken the shunt field exactly as the field of a series wound motor is weakened as it gathers speed. A shunt motor reversed in this way therefore develops series motor characteristics. But as I use this 35 method of reversing only for side tracking and switching within the stations where the car is under control of the operator, this feature is not objectionable. This method of reversing avoids the use of an extra contact 40 conductor rail, which would otherwise be necessary to provide a separate return connection from the shunt field for reversing the current through it.

45 The manual control of the car above described, *i. e.*, by means of controllers, is used only in or near the stations. At other points the movement of the car is independent of the operators, but subject to the automatic control of a block system.

50 Referring now to Figs. 5, 6, 7, 8, 9 and 55 10, T_3 represents the track rails, T_1 the shunt field conductor rail and T_2 the armature conductor rail as before. I_1 , I_2 , etc., are insulators serving to divide the track or contact 60 conductor rails into the sections above referred to.

65 At the approach to each station it will obviously be necessary to provide means for bringing the car to rest. In Fig. 5 the method of accomplishing this at a terminal

station is shown. This is accomplished by disconnecting the armature conductor rail T_2 from the source of current Sc (connected to positive main pm and to negative main nm) and connecting it to the track rail T_3 70 through a resistance while the field winding F_1 is separately excited at full strength, as already described. The minimum safe resistance in the armature circuit is determined by the speed of the car, and as the car is retarded the resistance can therefore be cut out step by step. In Fig. 5, the sections of the armature conductor rail $I_1—I_2$, $I_3—I_4$, $I_4—I_5$, $I_5—I_6$ are each connected to the track rails T_3 through successively smaller portions of the resistance or rheostat R_2 . In the drawing I_1 is not shown but is assumed to be on the armature conductor rail to the right of I_2 . The section $I_2—I_3$ is connected to the positive main pm , for reasons that will 75 be explained later. The sections of the armature contact conductor rail T_2 , such as $I_1—I_2$, etc., which are for braking normally connected to the track rails T_3 I call "retarding sections." The section $I_2—I_3$ I call an "equalizing section." The whole series 80 collectively I call a "braking section."

The field conductor rail T_1 throughout the retarding sections, as well as elsewhere, is likewise divided into sections (as at I_{51} , I_{52} , I_{53} , etc., Fig. 5) which have to do with the system of indicating in the stations the position of the cars in transit and also with the block system, both of which will be described later. Each section of the field conductor rail receives current through a series solenoid in the relays R_{21} , R_{22} , etc. These series solenoids are of negligible resistance so that the field conductor rail may, except in the case of sections that are under the control of 105 controllers, be considered to be in permanent connection with the positive main pm , causing the motor field F_1 to be excited as stated.

The operation of the retarding sections will be better understood by reference to Fig. 58. In this figure, the full line $l\ c$ is the curve of retardation of a loaded car from 30 miles per hour to rest, ordinates being proportional to speed and abscisse to distances. In the case illustrated, on the 115 first retarding section, *i. e.*, $I_1—I_2$, the speed is retarded from 30 to 15 miles per hour. Upon the equalizing section $I_2—I_3$, the motor on the car receives current from the source of power tending to drive it, but the resistance interposed between it and said source is so calculated that the torque developed by the motor is insufficient to overcome the resistance of the car to forward motion, which therefore continues to be retarded, though at a reduced rate. The car is retarded on the equalizing section from 15 to 10 miles per hour. On the remaining retarding sections, the speed is reduced from 10 to 5 miles per hour, from 5 to $2\frac{1}{2}$ miles 120 and finally to rest. The time required for the car to stop is 130

per hour and from $2\frac{1}{2}$ miles per hour to rest respectively.

In Fig. 58 the dotted line $e\ e$ is the curve of retardation of an empty car arriving at the same speed as the loaded car.

The function of the equalizing section is as follows:

The braking effect of a short-circuited motor armature whose field is separately excited at constant strength is, with a given resistance in the armature circuit, proportional to the speed. In other words, for a given speed it is the same for both the loaded and empty cars. But at a given speed the empty car possesses less energy than the loaded car, consequently it will be retarded more rapidly. In the case illustrated in Fig. 58 the empty car reaches the equalizing section with a speed of $13\frac{1}{2}$ miles per hour, as compared with 15 for the loaded car. At this reduced speed, however, the empty car receives a greater current from the source of power than did the loaded car, and gains in speed relatively to it. It leaves the equalizing section with a speed of 11 miles per hour as compared with 10 for the loaded car. From this point it begins again to be retarded more rapidly than the loaded car and finally comes to rest at the same spot (20, Fig. 58).

With any system of braking depending upon friction there is not only a great variation in the distance required to bring a train to rest on account of variation in the coefficient of friction, but there is also a great difference between empty and loaded cars (100% or more). With dynamo-electric braking this variation is reduced to about 12 $\frac{1}{2}\%$. By means of the equalizing section, however, it can be further reduced to a negligible quantity.

It will be observed that on each of the retarding sections the speed is reduced in the same ratio (being halved in this case except that on the last section the speed is reduced to zero). The object of this is as follows:

The maximum braking effect at the beginning of each section may be fixed either by the adhesion of the driving wheels or by the capacity of the motor, but in either case it is the same for all the sections. It will therefore be obvious that in order to secure the maximum braking effect with a given number of sections the mean braking effect upon all of them must be the same. But this condition is secured by so proportioning them that the braking effect is the same at the final end of all the sections, or, in other words, that the ratio of the initial and final braking effect for all the sections is constant. But the braking effect is proportional to the speed. Therefore, to secure the most effective braking the ratio of reduction in speed must be the same for all the retarding

sections. This can be expressed mathematically as follows:

$$\frac{S_2}{S_1} = \frac{S_3}{S_2} = \frac{S_4}{S_3} \text{ etc.}$$

in which S_1 , S_2 , S_3 and S_4 , are the speeds at the beginning of the successive retarding sections. If this law is followed it will be found that the successive retarding sections become shorter and shorter as in Fig. 58.

The retarding sections are normally at the entrance to the station, their function being to prevent the cars from entering the station except at the volition of the operator. When the cars have come to rest or been retarded to a safe speed, therefore, it is necessary that the operator should be able to cause them to enter the station.

This is accomplished by connecting the retarding sections to a controller in the station by means of which the operator may by a movement of a lever disconnect them simultaneously from the track rail and connect them to the source of power.

In Fig. 5 this controller is shown at C_1 . It will be observed that the retarding section I_1-I_2 is permanently connected through the rheostat R_2 to the track rail and the equalizing section I_2-I_3 is permanently connected through the rheostat R_1 to the positive main pm .

The operator thus has no control over the car until it has been retarded to a safe speed. The remaining retarding sections are, however, connected to the fingers 22, 23 and 24 of the controller C_1 , and in the position shown in Fig. 5, these fingers are connected through the drum to the fingers 25, 26 and 27. Thence 25 is connected directly to the track rail and 26 and 27 are connected to the track rail through the rheostat R_2 as previously stated.

The connections made by the drum of this controller in this (the braking) position are shown again for clearness in Fig. 20, side by side with the connections made by it in the alternative or starting position (Fig. 21). From this figure it will be seen that in the starting position the fingers 22, 23 and 24 are connected to the finger 21, and from Fig. 5 it will be seen that the finger 21 is connected through the rheostat R_1 to the positive main. In this case there are no reversing or through positions of the controller. The functions of the finger 28 and the solenoid 29 will be explained later.

The braking section ends at I_6 , and at this point another section of the track, which I call the "approach section," begins. This section is under the control of the controller C_2 , which is similar to the controller that has already been described in connection with Figs. 1, 2, 3 and 4. It will be remembered that it has four positions, viz: reversing, braking, starting and through. For clearness, the drum connections in each of

110 115 120 125 130

The braking section ends at I_6 , and at this point another section of the track, which I call the "approach section," begins. This section is under the control of the controller C_2 , which is similar to the controller that has already been described in connection with Figs. 1, 2, 3 and 4. It will be remembered that it has four positions, viz: reversing, braking, starting and through. For clearness, the drum connections in each of

these positions are shown again in Figs. 22, 23, 24 and 25. The object of the through position may now be understood. It is that this approach section I_6 — I_7 may serve as an equalizing section for trains that have been admitted from the braking section, the operation being the same as that of the equalizing section already described. By this means cars arriving at less than the desired speed are accelerated and others arriving at a greater speed than that desired are retarded.

The approach section in general enters the station and is used for shunting or switching the cars, hence the reversing, braking and starting positions.

From the approach section the car normally passes over a switch point or system of switch points which may direct it on to an unloading section or upon a siding, at the will of the operator. In Fig. 5, the unloading section is from I_7 to I_8 and a siding is shown from I_{10} to I_{11} . I_8 to I_9 is a loading section.

These three sections in the order last named are under the control of the controllers C_3 , C_4 and C_5 respectively. The controllers are all similar to each other, but differ from the controller C_2 in that they have no through position, the place of which is taken by a "neutral position", in which all connections to the section are interrupted. The drum connections for the several positions of these controllers are shown in Figs. 26, 27, 28 and 29. They are similar to those already described in connection with C_2 except that instead of the two fingers 13 and 14 connected through different resistances to the positive main pm , there is but one, indicated at 33.

It will be noticed that the several controllers do not all receive current through the same rheostats, C_1 for instance, being connected through R_1 , and C_2 , C_3 , C_4 and C_5 through R_5 . Similarly, they are not short-circuited to the track rails through the same rheostats, C_1 being connected through R_2 , and C_2 , C_3 , C_4 and C_5 through R_4 . The object in this is to avoid the use of the same rheostats for two sections upon which it may be desired to move trains at the same time, for if two trains were to take current simultaneously through the same rheostat the current and consequently the fall of potential through the rheostat would not be the same as when only one was taking current and neither train could develop the required starting torque.

It will be noted that the field conductor rail T_1 and the track rails T_3 of each of these sections under control of controllers having a reversing position are insulated from the adjoining sections as well as the armature conductor rail (as at I_{58} and I_{60} Fig. 5). This is necessary, as in reversing,

the field conductor rail is completely changed in its polarity, while a considerable difference of potential is created between the section of the track rail and adjoining sections owing to its being connected to the negative main nm through a resistance as previously explained.

It is to be understood that the arrangement of an actual station may be more or less of a modification of the arrangement described while conforming to it in that there will be one or more sections completely insulated from adjoining sections and each under the control of a separate controller, whereby cars can be moved on one section without disturbing those on another.

When a car passes over the insulators I_9 or I_{11} , it leaves the control of the operator at the station and enters upon a series of sections, I_9 — I_{11} — I_{12} , I_{12} — I_{13} , I_{13} — I_{14} and I_{14} — I_{15} , which I call "accelerating sections." The accelerating sections are normally connected to the positive main through successively less portions of the rheostat R_5 . The field conductor rail is likewise subdivided, but as already explained, all of its sections, except in the case of sections that are under the control of controllers, are permanently connected to the positive main pm .

As the car advances over the accelerating sections, therefore, the resistance that was interposed in the armature circuit at starting is cut out step by step until at I_{15} the armature is receiving full voltage, the field F_1 being meanwhile separately excited to full strength, causing the car to be accelerated to full speed.

I can attain the same result by supplying the accelerating sections with successively increasing voltage from independent sources.

The section I_9 — I_{11} — I_{12} is connected to the positive main through the contactor K_1 , which has to do with the block system to be explained later. With this exception, the connections of the accelerating sections of the terminal station shown in Fig. 5 with the positive main are permanent.

The condition as to the proportioning of the accelerating sections which gives the most effective acceleration with a given number of sections is different from that obtaining in the case of braking, and can best be stated mathematically.

If S be the full speed of the car, s the speed at any instant, T the motor torque and R the total resistance of the armature circuit, then with the field separately excited to full strength:

$$T = \text{const.} \frac{(S-s)}{R}$$

Therefore, with the same initial torque for all the sections, to obtain the same final

torque and consequently the same mean torque the following condition must be fulfilled:

$$5 \quad \frac{S-s_1}{S-s_2} = \frac{S-s_2}{S-s_3} = \frac{S-s_3}{S-s_4} \text{ etc.}$$

in which $s_1, s_2, \text{ etc.}$, are the speeds at the beginning of the successive accelerating sections. This equation therefore expresses a 10 condition of the most effective acceleration with a given number of sections.

At the intermediate station, (Fig. 8), approach, unloading, loading and siding sections ($I_{28}-I_{29}$, $I_{29}-I_{30}$, $I_{30}-I_{31}$ and 15 $I_{32}-I_{33}$), under control of the controllers C_8, C_9, C_{11} and C_{10} respectively, are found, but otherwise this station differs materially from the terminal station just described in ways that can best be explained in connection 20 with the block system.

It has already been stated that the field conductor rail is divided into sections, each of which receives current through a series 25 solenoid actuating a relay. For this purpose, among others, the positive main pm is carried along the line from one end to the other and is everywhere indicated by the sign + (Figs. 5-10 inclusive).

The construction of these relays will be 30 understood by reference to Figs. 38-43 inclusive.

The relay is arranged with its axis horizontal.

C_{12} is an iron core passing through the 35 solenoids S_{11} and S_{12} , of which the former is the low resistance series solenoid through which the sections of the field conductor rail are supplied. When S_{11} is energized it draws the core C_{12} in the direction of the 40 arrow in Fig. 38. W_3, W_3 are contacts between which passes the sleeve S_3 which is mounted upon the brass rod S_4 forming a continuation of the core C_{12} . The sleeve S_3 is metallic and in one position makes contact 45 between the contacts W_3 . At the end which comes between these two contacts when the core is to the right, however, the sleeve S_3 is surfaced with an insulating material 100 and in this position the connection 50 between the two contacts is interrupted. The sleeve S_3 is made free to slide upon the rod S_4 in order that it may lag back during the first half of the motion of the core C_{12} in the opposite direction to the arrow 55 in Fig. 38 and compress the spring S_5 , which during the remainder of the movement re-expands and quickens the breaking of the circuit.

R_{21}, R_{24} , and R_{25} , Fig. 5, are relays of the 60 type just described. Being represented diagrammatically, the contacts are shown between the solenoids instead of at one end, but this does not change the principle of operation. When the solenoid nearest the 65 contacts is energized, the connection between

the contacts must be considered to be established. Relays of this type will be referred to hereinafter as single-ended relays.

R_{26}, R_{27}, R_{28} , etc., Fig. 6, are relays exactly similar to those just described except 70 that the contact mechanism W_3, W_3 , at the one end is duplicated at the other end where the stationary contacts are W_6, W_6 . Relays of this type will be referred to as double-ended relays, and the contacts W_6 as "interrupting" contacts. 75

Figs. 42 and 43 illustrate a modified form of relay intended to be operated with its axis vertical so that the weight of the core C_{12} and lead weight 101 in falling from position shown break the contact, thus dispensing with the shunt solenoid S_{12} . Relays of this type will be called gravity relays. R_{22} , 80 Fig. 5, and R_{27} , Fig. 8, are of this type. These two relays are likewise shown diagrammatically and notwithstanding their position it must be understood that when the solenoid is energized, connection is established between the nearest set of contacts. 85

Referring again to Fig. 5 and taking the 90 relay R_{24} for illustration, it will be seen that there is a connection from the positive main through the series solenoid S_{11} to the field conductor rail section $I_{56}-I_{58}-I_{59}$, so that when there is a car upon this section the current 95 passing to the field of its motor will excite the solenoid S_{11} and establish connection between the contacts W_3 .

It will be noticed that paralleling the 100 positive main is a series of conductors 50 to 63, Fig. 5. If these be traced through it will be found that they connect through the electric lights L_1, L_2, L_3 , etc., at both the 105 terminal and intermediate stations, with the negative main nm , so that if any one of these conductors be energized the corresponding lights will be lighted in both stations. The rheostats R_{19} and R_{20} regulate the voltage upon these lights.

Referring now to Fig. 46, it will be seen 110 that upon the control table there is a box D provided with an opaque cover 102 through which is cut a slot 103 representing exactly to a small scale the portion of the line extending between the two stations. This slot 115 is crossed by partitions 104 which divide it into sections corresponding to the sections of the field conductor rail. In the space inclosed between each pair of partitions is a small electric light which when lighted 120 illuminates the section of the slot to which it belongs. These lights are the lights L_1, L_2, L_3 , etc., just referred to, and there is one of these diagrams at each of the stations.

In Fig. 5 a car is shown upon the section 125 $I_{56}-I_{58}-I_{59}$ and connection is therefore established between the contacts W_3 of solenoid R_{24} . One of these contacts is connected to the positive main and the other to the conductor 50. Under these circum- 130

stances, therefore the lights L_1 will be lighted, indicating to the operators at both stations that there is a car or train on this section.

5 Similarly a car on any section between the stations will indicate its presence upon the diagrams D.

When the car passes onto the section I_{59} — I_{60} , it operates the relay R_{25} in the manner described and lights the lights L_2 , through the conductor 51. But it will be observed that there is also a connection from the conductor 51 through the shunt solenoid S_{12} of the relay R_{24} to the negative main (or track rail), so that when the conductor 51 is energized the solenoid S_{12} is likewise energized. This operates the relay R_{24} to break the connection between the contacts W_3 and extinguishes the lights 20 L_1 . If a car should break down in transit, therefore, the light of the last section that it passed onto will remain lighted even if it should cease to take current through the series solenoid of the corresponding relay. When there are sections of the line not provided with relays and indicator lights as is sometimes the case in the stations, however, the relay of the last section is of the gravity type as shown at 25 R_{22} , Fig. 5, and R_{37} , Fig. 8.

We will now consider the block system which has already several times been referred to.

The function of the block system is to 30 prevent collision with the following train in case (for instance) a train should stop for any reason between stations or be left standing upon a braking section.

This is accomplished by dividing the line 35 into sections called "block sections", each of which is capable of bringing a train to rest from full speed and re-starting it without injury, and the principle of operation is to maintain at all times a closed block section between trains in transit.

The method of bringing a train to rest in a block section is the same as that employed upon the braking section already described, *i. e.*, to disconnect the armature conductor rail from the source of power and connect it to the track rail through a suitable resistance while the field is excited to full strength from the field conductor rail. Similarly the train is re-started by connecting the armature conductor rail to the source of power through a suitable resistance.

To make the operations of braking and accelerating more effective and thereby reduce the length of the block section, the latter is subdivided into a number of sections, some of which serve to cut out, step by step, the resistance in the armature circuit, when the armature is connected to the track rail in braking and others to cut out

step by step the resistance interposed between the armature and the source of power in starting.

The operation of changing the connections to the armature conductor rail is performed by contactors similar to that shown in Figs. 34, 35, 36 and 37.

Referring to these figures, C_{13} and C_{14} are iron cores passing through the solenoids S_6 and S_7 respectively, and attached by the links L_{60} , L_{61} , which are of insulating material, to the arm A_2 . The arm A_2 is pivoted at P_7 , and carries at its ends the blades B_5 , B_6 , which are adapted to enter between and make contact with the contacts C_{15} or 75 with similar contacts C_{16} (not shown) at the opposite side.

The arm A_2 is electrically connected with the terminal P_1 , and the contacts C_{16} and C_{15} are respectively electrically connected 80 with the terminal P_3 and with a similar terminal P_2 (not shown) placed symmetrically opposite to P_3 .

The solenoids S_7 , S_6 have respectively electrical connection with the terminal P_6 90 and with a similar terminal P_5 (not shown) placed symmetrically opposite to P_6 , P_4 serving as a common return connection for both.

The arm A_2 and the frames F_3 carrying 95 the contacts, etc., are insulated from the ironwork of the contactor and from each other by the insulators I_{105} .

When the solenoid S_6 is energized, the arm A_2 makes contact with the contacts C_{15} 100 and thus establishes connection between P_1 and P_2 . When the solenoid S_7 is energized, connection is similarly established between P_1 and P_3 .

The blades B_5 , B_6 , are pivoted at P_8 and 105 P_9 respectively and are normally held in the position shown by the springs S_9 and S_{10} respectively. When the arm A_2 starts to move the blade in contact lags behind, deflecting the spring, and when it finally 110 disengages itself from the contacts the spring quickens the breaking of the circuit.

The contacts C_{15} are pressed together by the springs S_8 , which bear upon the disks D_1 , which in turn are soldered to the flexible connectors C_{17} and serve to convey the current from the contacts to the terminal P_2 . The disks D_1 , however, leave the contacts C_{15} free to rotate, and the lagging of the blade B_5 as above described tends to 120 make them do so, thus presenting a fresh surface each time for the making and breaking of the circuit.

The flexible connector C_{18} serves to convey the current from each blade to the central frame and thence to the terminal P_1 . 125

The axes of the two contacts C_{15} are each set at a slight angle, 1 degree, for example, with the horizontal and there is consequently an angle of 2 degrees between the 130

two. This renders the entry of the blade B_5 smoother.

The inverted position of the contacting mechanism lends itself to the immersion of the mechanism in an oil bath which helps to extinguish the arc and also improves the working and durability of the apparatus.

In Fig. 5 one of the contactors just described is indicated diagrammatically at K_1 . The common terminal P_1 is here shown for clearness as two terminals, the identical function of which is, however, shown by their being connected together everywhere. It is to be at all times understood that the contacts on the side of the contactor that is energized are connected together. Thus, in the position shown the solenoid S_7 is assumed to have been last energized and the terminals P_1 and P_3 are connected. In this position it will be observed that the conductor rail section I_9 — I_{11} — I_{12} , is short-circuited to the track while in the alternative position it is connected through the rheostat R_5 to the positive main.

Referring now to Fig. 7:

This figure illustrates a typical block section complete. It will be seen that as regards the armature conductor rail, it is subdivided into four sections. The first of these, I_{19} — I_{20} , is intended to retard the car at need from full speed to half speed, the second, I_{20} — I_{21} , from half speed to quarter speed, and the third, I_{21} — I_{22} , from quarter speed to rest. The car coming to rest near the initial end of the section I_{21} — I_{22} , this section is also intended to accelerate it upon restarting to a speed approximating two-thirds of full speed (determined according to the law given above for accelerating sections). The section I_{22} — I_{23} is intended to further accelerate the car to five-sixths of full speed, at which the motor can safely receive the full voltage of the mains upon entering the next block section.

It will be seen that the field conductor rail throughout this block section is sub-divided into five sections, which are therefore not co-terminus with or of the same lengths as the sections of the armature conductor rail. There must be at least one section of the field conductor rail for each block section. Any further sub-division of this conductor rail is purely a matter of choice, and merely serves to enable the movement of the trains to be observed more closely at the stations.

Referring to the section I_{19} — I_{20} , it will be found that this receives current direct from the positive main through the contactor K_8 in one of its positions, while in the other position of this contactor it is connected through the rheostat R_{10} to the track rail for braking.

Similarly the conductor rail section I_{20} — I_{21} is connected to the track rail through the rheostat R_{10} (a less portion of it than

before) in one position of the contactor K_{10} for braking. In the other position of K_{10} this section is connected to the common terminal P_1 of the contactor K_9 , which in one position connects it directly to the positive main and in the other position connects it to the positive main through the rheostat R_{11} for accelerating. The two contactors K_9 and K_{10} in co-operation may therefore either short-circuit the section I_{20} — I_{21} to the track rail through a suitable resistance for braking, or connect it to the positive main through a suitable resistance for restarting the car, or connect it to the positive main direct for through cars. These three conditions are all that are required for the operation of closing or opening this part of the block system.

The conductor rail section I_{21} — I_{22} is also provided with two contactors K_{11} and K_{12} , which operate in the same way as the contactors K_9 and K_{10} , except that in this case the contactor K_{12} in one of its positions connects the section directly to the track rail with no resistance interposed.

The conductor rail section I_{22} — I_{23} is provided with only one contactor K_{13} , which in one position connects the section to the positive main through the rheostat R_{12} (a less portion of it than in the case of the contactor K_{11}) and in the other position connects it to the positive main direct.

It will be observed that the section I_{19} — I_{20} has only one contactor and no starting position because it is expected that the car will never come to rest on or have to be restarted from this section, while the section I_{22} — I_{23} has only one contactor and no braking position because it is expected that the car will always come to rest before reaching this section.

It is also to be noticed that the successive sections are in the braking position by connections to the track rail through progressively smaller resistances; or in the alternative starting position the successive sections are connected to the positive main likewise through progressively smaller resistances.

It will be obvious that the block section could be divided into a greater or less number of sections without affecting its principle of operation.

It should be noticed that at the beginning of the block section illustrated in Fig. 7 there is a reverse curve. This is assumed to be of too short a radius to be taken at full speed. Accordingly, provision is made in the preceding block section, illustrated in Fig. 6, to retard the car to the safe speed before it reaches this curve. For this purpose the last conductor rail section of the block section, I_{18} — I_{19} , is normally short-circuited through the rheostat R_6 , this position corresponding to the full voltage position of the analogous contactor K_{13} . In other respects

the operation of this block section is the same as that described.

Returning to Fig. 7:

The closing and opening of this block section is effected as follows:

It will be found that the S_7 solenoids of Fig. 7, which in every case operate the contactors to close the block section, are all connected to the conductor 62, while the other 10 or common terminal of these solenoids are connected to the track rail or negative main. If, therefore, the conductor 62 be energized, the entire block section will be closed. This is the position in which the contactors are 15 shown in the figure. In Figs. 14, 15 and 16, the contactors of this block section are for clearness shown diagrammatically by themselves, and Fig. 14 also illustrates the closed section.

20 The solenoids S_6 of the contactors K_{10} and K_{12} will be found to be connected to the conductor 64, so that if this conductor be energized these contactors will be thrown into the normal or opening position. If the remaining contactors of this block section then 25 remain as they were, viz., in the closing position, the sections $I_{20}-I_{21}$ and $I_{21}-I_{22}$ will be found to be connected to the positive main through the rheostats R_{11} and R_{12} respectively, which are calculated to give the starting voltage. The section $I_{22}-I_{23}$ remains at the accelerating position. The 30 whole block section is therefore in a position to restart the car from any point on $I_{20}-I_{21}$ or $I_{21}-I_{22}$, and accelerate it to the speed at which it may safely pass onto the 35 next block section and receive full voltage. This (the starting) position of the contactors of this block section is illustrated in Fig. 15.

40 It will be seen, however, that the conductor 64 is also connected through the interrupting contacts W_6 , in series, of the double-ended relays R_{31} , R_{32} , R_{33} , R_{34} , and R_{35} to the S_6 solenoids of the remaining contactors of this block section, viz., K_s , K_9 , K_{11} and K_{13} , through the conductor 64a. If, therefore, there is no interruption in the 45 circuit 64a at any of these relay contacts W_6 the contactors K_s , K_9 , K_{11} and K_{13} will likewise be thrown into the open block position when the conductor 64 is energized. This will result in supplying full voltage to all the sections of this block section, or, in 50 other words, in throwing it completely open.

This position of the contactors is illustrated in Fig. 16.

55 The connection from the conductor 64 through the interrupting contacts W_6 of the relays R_{31} to R_{35} inclusive and conductor 64a will be broken if there is no car upon this block section, but if there is a car anywhere upon it the current to its field will cause the relay through which it passes to 60 make connection between its left-hand con-

tacts W_3 and break the connection at its interrupting contacts W_6 , thus breaking the connection to the S_6 solenoids of the contactors K_s , K_9 , K_{11} and preventing them from operating.

To recapitulate therefore, this block section is closed when the conductor 62 is energized and when the conductor 64 is energized it is thrown either into the starting position or into the open position, depending upon whether there is a car upon this block section at the moment.

The connections made by the contactors of the first block section illustrated in Fig. 6 in each of their several positions are clearly shown in Figs. 11, 12 and 13. They are the same as for the second block section except that the positions of the last contactor in the series are reversed, for the reasons already given.

It has been stated that the principle of operation of the block system is to maintain at all times a closed block section between trains during their transit. This is carried out by causing each train as it enters a new block section to close the block section that it has just left and, if the second block section behind it was previously closed, to open it.

When the operator at the terminal station, Fig. 5, wishes to despatch a car standing upon the loading section, I_8-I_9 , he moves the controller C_5 manually, in a manner to be hereinafter described, into the starting position. The car at once leaves the loading section and enters upon the exit section, I_9-I_{11} , $I_{11}-I_{12}$. In so doing, the current passing to the field F_1 of the motor operates the relay R_{24} and energizes the conductor 50, lighting the lights L_1 in both stations. Proceeding, the car enters the section $I_{12}-I_{13}$. This energizes the S_{11} solenoid of the relay R_{25} , thus energizing conductor 51 and lighting the lights L_2 and returns the relay R_{24} to its normal position, extinguishing the lights L_1 . But it will be noticed that there is also a connection from the conductor 51 to the S_7 solenoid of the contactor K_1 so that when this conductor is energized the contactor K_1 is thrown into the closing position, connecting the conductor rail section $I_9-I_{11}-I_{12}$ directly to the track rail. If a second train is now despatched it will come to rest by braking in the exit section.

Continuing its course, the train passes over the sections $I_{12}-I_{13}$, $I_{13}-I_{14}$ and $I_{14}-I_{15}$, by which time it has been accelerated to full speed. The train now enters upon the first block section $I_{15}-I_{19}$, Fig. 6, 125 and passes over it, lighting and extinguishing successively the lights L_3 , L_4 , L_5 , L_6 and L_7 , the exit section remaining closed meanwhile.

Upon passing I_{19} , Figs. 6 and 7, the train 130

enters upon the second block section, and in so doing it operates the relay R_{31} , Fig. 7. This energizes the conductor 57, extinguishing the lights L_7 and lighting the lights L_8 . 5 But the conductor 57 will be found to have connection with all the S_7 or block closing solenoids of all the contactors, K_2 , K_3 , K_4 , K_5 , K_6 , and K_7 , of the first block section, as well as with the S_6 or opening solenoid of 10 the contactor K_1 . When conductor 57 is energized, therefore, the exit section will be opened and the entire first block section simultaneously closed.

Similarly, upon passing I_{23} , Figs. 7 and 8, 15 the conductor 62 is energized by relay R_{36} whose solenoid S_{11} is energized through solenoid 49. It will be remembered that this closes the entire second block section, $I_{19}-I_{23}$, Fig. 7. But it will also be found 20 that the conductor 62 has a connection with the S_6 or opening solenoids of the first block section (Fig. 6). Thus, as there is no car on the first block section at the moment, it will be opened simultaneously with the closing 25 of the second block section.

We now come to the third block section, which as already stated, includes the intermediate station (Fig. 8).

When the switch points P_{10} , P_{11} , which are 30 worked simultaneously in a manner to be described hereinafter, are in the "past" position *i.e.*, for directing the train past the station, the third block section automatically, in a manner that will be explained herein- 35 after, takes its place in the series of block sections, of which the fourth and fifth block sections illustrated in part in Figs. 9 and 10 respectively are a continuation. Under these circumstances the third block section operates exactly like any other block section, closing each time a train passes off it and opening when the train has traversed the next block section.

When the switch points P_{10} , P_{11} , are 45 thrown into the station position, however, the third block section, in a manner to be explained, automatically adapts itself to the station requirements, that portion in advance of the switch points P_{10} becoming a braking 50 section under control of the operator in the station, while the portion following the switch points P_{11} becomes an accelerating section, the approach, unloading, loading siding and exit sections being found in the 55 normal relation to each other.

In Fig. 8 the switch points P_{10} , P_{11} , are assumed to be in the station position and a car X_1 , is shown in the position of having just come to rest upon the braking section. 60 In conformity with this circumstance, the first block section behind it (Fig. 7) is closed, and the second one behind it (Fig. 6) is open.

A car X_2 is shown in transit on the first 65 block section (Fig. 6) and in consequence the

exit section at the terminal station (Fig. 5) is shown closed. A car X_3 is shown held up upon this exit section.

Under these conditions, if the car X_1 remains in the position shown, the car X_2 70 will presently come to rest in the second block section (Fig. 7). In entering this section car X_2 will close the first block section (Fig. 6) and open the exit section section (Fig. 5) releasing the car X_3 . The car X_3 will then advance and come to rest upon 75 the first block section (Fig. 6). If a fourth car is now despatched it will be held up in the exit section. Thus all the block sections will be occupied and no further cars 80 can be despatched until the car X_1 is moved.

When the car X_1 is brought into the intermediate station (Fig. 8) X_2 and X_3 will each move up one block section, or if the switch points P_{10} , P_{11} , are moved to the 85 "past" position they will pass the intermediate station at full speed with two block sections separating them, one of these two block sections always closed.

It will be observed that the third or intermediate station block section (Fig. 8) has subdivisions corresponding to those of the braking section and accelerating sections of the terminal stations, and these are considerably more numerous than are the sections 90 of an ordinary block section. The principle of operation, however, is precisely the same. Each section has at least one contactor and those sections of the braking section upon which the trains are expected to stop are provided with two contactors each, giving the braking, starting and through positions desired in the way that has already been explained. Thus K_{14} belongs to section 95 $I_{23}-I_{24}$, which retards from 30 to 15 M. P. $H.$; K_{15} belongs to the section $I_{24}-I_{25}$, which is the equalizing section connected to positive main pm through resistance R_{15} ; K_{16} and K_{17} belong to the section $I_{25}-I_{26}$, which 100 retards from 10 to 5 M. P. $H.$; K_{18} and K_{19} belong to section $I_{26}-I_{27}$, which retards from 5 to $2\frac{1}{2}$ M. P. $H.$; and K_{20} and K_{21} belong to section $I_{27}-I_{28}$, I_{24} , which brings the car or train to rest. Likewise, K_{24} , K_{25} and K_{26} 105 belong to the accelerating sections $I_{35}-I_{36}-I_{37}$; $I_{37}-I_{38}$ and $I_{38}-I_{39}$ respectively, while K_{22} belongs to the section that extends between the switch points and K_{23} belongs to the exit section.

It has been stated that when the switch 120 points P_{10} , P_{11} , are in the station position the braking section is under control of the operator in the station. This is by means of the controller C_6 . As the control of a block section is effected by means of two 125 conductors only, connected the one to all the S_6 solenoids in parallel and the other to all the S_7 solenoids in parallel, C_6 has only three fingers, one of which, 38, communicates with the positive main. It will 130

be seen that the finger 39 is connected to the finger 44 of controller C₇ and thence through the drum to the finger 45, whence the connection, branching at 82, 83, 84, 85, 5 86, etc., is to the S₇ solenoids of all the contactors belonging to this section. With the controllers C₆ and C₇ in the position shown, therefore, all the contactors of the braking section will be thrown into the braking 10 position and all those of the accelerating section's into the accelerating position. Similarly, the finger 40 is connected to the finger 43 of the controller C₇ and thence through the drum to the finger 47, whence 15 the connection is to the S₆ solenoids of the contactors K₁₇, K₁₉, and K₂₁, these being the contactors of the three double sets which, it will be remembered must alone be operated to throw the braking section 20 into the starting position. (If the remaining contactors were operated at the same time, the through and not the starting position would result.) The contactors of the accelerating section, when once thrown into 25 the accelerating position, are for obvious reasons independent of the controller C₆ and remain in that position so long as the switch points P₁₀, P₁₁ are in the station position.

Although Fig. 8 shows the controller C₆ 30 and the contactors in the braking position, the connection within this controller is shown again in Fig. 30 to facilitate comparison with the connection made in the alternative or starting position shown in 35 Fig. 31. Likewise, the connections made by the contactors in the braking position are shown again in Fig. 17 to facilitate comparison with the connections made in the starting position shown in Fig. 18.

40 It has been shown that the connections by which the controller C₆ operates the braking section are carried through the controller C₇ and are dependent upon connection being established in the drum of the 45 latter between the fingers 44 and 45 and 43 and 47 respectively, as is the case in Fig. 8 and also in Fig. 32. In Fig. 33, however, which shows the alternative position of the controller C₇, these connections are interrupted. But the controller C₇ is operated 50 simultaneously with the switch points P₁₀, P₁₁ and the position shown in Fig. 33 is the "past" position. Hence, in the past position the control of the braking section 55 is taken out of the hands of the operator.

When the switch points have been in the station position and are returned to the past position, this whole block section must automatically assume a position appropriate to the circumstances. That is to say, if there is a train at the moment upon the fourth block section, then the third block section must be closed; otherwise it must be open. To effect this automatic control

I provide the relay R₄₂, which I call a 65 "master relay." This relay is double-ended and has no series solenoid, but is equipped with two shunt solenoids adapted to work upon the full voltage of the mains. It will be seen that the conductor 69, (Figs. 8 and 70 9), which is the one that is energized when the train enters the fourth block section, connects through one of these solenoids, S₂₄, to the negative main, while the conductor 74 (Figs. 8, 9 and 10), which is the one 75 that is energized when the train enters upon the fifth block section, connects through the other solenoid, S₂₃, also to the negative main. Hence, as long as there is a train on the 80 fourth block section, the contacts W₅ will be connected together, but when the train has passed to the fifth block section it will set the relay R₄₂ in the other position and leave it so, with the contacts W₄ connected together. 85

Now, it will be found that the contacts W₅ connect from the positive main to the finger 42 of the controller C₇, and when this controller is in the "past" position, as in Fig. 33, the finger 42 is connected through 90 the drum to the fingers 45 and 46. But it has already been shown that the finger 45 communicates with the S₇ solenoids of all the contactors of the third block section and, when energized, throws this section 95 into the closed position, and the finger 46 will be found to communicate with the conductor 64, which, it will be remembered, opens the second block section. Hence, with the controller C₇ in the "past" position, the 100 third block section is closed and the second block section is opened whenever a car enters the fourth block section, which is in accordance with the established principle 105 upon which the block system operates.

The contacts W₄ connect in a similar manner to the finger 41 of the controller C₇, and when this controller is in the "past" position, as will be seen from Fig. 33, the finger 41 is connected through the drum to the fingers 47 and 48. But the finger 47 has already been shown to communicate with S₆ solenoids of the contactors K₁₇, K₁₉, and K₂₁, which if operated alone would give the starting position, and the finger 48 will be 110 found to connect in series through the "interrupting" contacts, W₆, of all the relays associated with this block section, viz., R₃₆, R₃₇, R₃₈ and R₄₃, and thence to the S₆ solenoids of the remaining contactors. When 115 energized together therefore, the fingers 47 and 48 throw the whole block section into either the starting or the through position (depending upon whether there is a car upon it at the moment or not). Hence, with the controller C₇ in the "past" position, the third block section is opened by a car 120 passing on to the fifth block section, which

again is in accordance with the principle of operation of the block system.

The master relay R_{42} , remains in the position in which it was last set, even after its solenoids cease to be energized. Hence, if, for example, the third block section is in the braking position when the switch points are thrown into the "past" position and the circumstances are such that it should be open (i. e., there is no car on the fourth block section) it will be automatically opened by the master relay R_{42} .

Additional precautionary devices are necessary to avoid certain further mischances, as, for example, that of two trains meeting at the trailing switch points P_{11} . To show how such a meeting is prevented, it will be necessary to explain the working of the control table, which is illustrated in Figs. 46-51, inclusive.

C_6 , C_7 , C_8 , C_9 , C_{10} and C_{11} are the controllers already described under these respective designating symbols. These controllers are rigidly bolted to the frame F_5 , S_{29} , S_{20} designating the ends of the shafts upon which the rotating controller drums are mounted. In the case of the controllers C_7 and C_8 , the mechanism by which they are operated is shown. The remaining controllers in the upper and lower tier respectively are operated by similar mechanism, which is omitted for simplicity.

The extremities of the shafts S_{29} are fitted with bevel gears G_3 , those of the controllers in the lower tier, as C_8 , being extended so as to bring the gears G_3 all at the same height. The gears G_3 mesh with gears G_4 , which are mounted on short sections of shafting S_{14} , S_{15} , S_{16} , etc., carried horizontally in the journals J_1 , J_1 , etc., the ends of these sections of shafting lying within the journals, which thus serve each for two sections. This will be more clearly understood from Fig. 50, which is a plan view of this mechanism. Upon each of these short sections of shafting is mounted a handle H_1 , H_2 , H_3 , etc., moving in a vertical plane, which thus serve to operate the controllers through the bevel gears. The handles H move through 30 degrees between their several positions, so that a total movement of 90 degrees, or 45 degrees from the vertical, in each direction suffices for four positions.

Upon the shafts S_{13} , S_{17} , S_{18} , and S_{19} are keyed the cams C_{19} , C_{20} , C_{21} and C_{22} respectively. Upon the shafts S_{14} and S_{15} are keyed the gears G_5 and G_6 . S_{20} is a countershaft extending nearly the full length of the control table and journaled at J_2 , J_2 . The countershaft S_{20} is driven by gear G_7 , which meshes with the gear G_5 . At one end it carries the cam C_{23} , and at the other end the cams C_{24} and C_{25} , which interlock with the

cams C_{19} , C_{21} and C_{22} respectively in a manner that will be presently described.

C_7 , it will be remembered, is the controller that is operated simultaneously with the switch points P_{10} and P_{11} . It is the handle H_2 , which operates this controller, that also operates the countershaft S_{20} . The three-way cocks, V_1 , V_2 , are likewise operated by this handle, through the lever L_{62} , which is mounted on the countershaft S_{20} , through the links L_{63} , L_{64} , and through the levers L_{65} , L_{66} . This is shown more clearly in Fig. 49, which is a sectional view taken on the line 9-9 of Fig. 46, looking toward the right. These three-way cocks, through connection with a reservoir not shown, containing compressed air, operate the switch points P_{10} , P_{11} , in a manner to be described later.

Fig. 51 is a diagrammatic view of the cams C_{19} to C_{28} , as well as of the handles H_2 and H_3 , all seen as if the shafts had been withdrawn and they had been laid flat in their correct relative positions in the plane of the paper. It will be seen that these cams are incomplete disks, so placed that the circles swept by two adjacent cams overlap. In every case they are notched out so that in some positions the space swept by one will be left clear by the other and in other cases it will not. Thus, it will be evident that as illustrated in Fig. 51, all the cams are free to turn except C_{19} , which is locked by the cam C_{26} . The diameters of the large and small cams are in the ratio of 2 to 1 and the gear ratio of G_5 to G_7 , etc., is the same. The angle subtended by the notches in the cams C_{23} , C_{24} , C_{25} , C_{27} and C_{28} is 60 degrees, corresponding to a motion of 30 degrees or one position by the actuating handles H_1 , etc. The cam C_{26} is notched for an angle of 180 degrees, or three positions; the cams C_{20} and C_{21} are each notched on one side for 60 degrees, or two positions and the cam C_{22} is notched on each side for 60 degrees or two positions.

The cams C_{21} and C_{22} belong to the handles H_6 and H_7 , which operate the controllers C_{10} and C_{11} . These are the controllers of the siding and the loading sections respectively, from either of which cars may be despatched that will have to pass the trailing switch points P_{11} before entering upon the line. The handles H_6 and H_7 are both shown in the neutral position N , while the handle H_2 is shown in the station position S . But suppose the handle H_2 to be set in the "past" position P . This involves a counter-clockwise rotation of one position and consequently imparts a clockwise rotation of one position to the cams C_{24} and C_{25} . It is evident that in this position the handles H_6 and H_7 will be locked against the starting position A . In other words, when the switch points P_{10} , P_{11} , are in the "past" po-

sition the controllers C_{10} and C_{11} are locked against the despatch of a train from the station.

Conversely, if with the cams C_{24} and C_{25} in the position shown, either of the handles H_6 or H_7 are rotated one position into the starting position A, the corresponding cam C_{24} or C_{25} , as the case may be, and consequently the handle H_2 will be locked. In other words, when either of the controllers C_{10} or C_{11} is in the starting position the track points P_{10} , P_{11} , are locked in the station position.

It should be noted, however, that the cams C_{21} and C_{22} are free to move into the reversing position R or the braking position B, regardless of the position of the switch points, and conversely they do not lock the switch points when in any position but the starting position.

If the switch points P_{10} , P_{11} , were to be operated at moment when a train was passing over them, derailment would probably result. If they were operated when a train was approaching in the braking section there might be too sudden a change from the braking to the through position, or vice versa, causing a burn-out of the motors. Again, if a car had been despatched from the station but had not yet passed the trailing switch point P_{11} at the moment the switch points were operated, the result might be a collision with another car that had previously been standing on the braking section. For these reasons it is necessary that the switch points P_{10} , P_{11} , should be locked as long as the braking or exit sections are occupied by a car. This is accomplished as follows:

In Fig. 46, 49 is an inclosed magnet, comprising a solenoid and core, which is lifted when the solenoid is energized. The mechanism operated by this core is not shown in Fig. 46 as this view is not a favorable one for the purpose. But in Fig. 47, which is an elevational view of this end of the control table, this mechanism is clearly shown. D_2 is a pawl, pivoted at P_{12} with a hooked end which is adapted to enter either of the notches, N_1 , N_2 , in the cam C_{29} when the pawl D_2 is pressed upward by the rod S_{22} , which is actuated by the core of the magnet 49.

The cam C_{29} is mounted upon the counter-shaft S_{20} . Hence, when the hooked end of the pawl D_2 is in engagement with either of the notches N_1 , N_2 , the handle H_2 is locked.

Referring now to Fig. 8, it will be found that the various sections of the field conductor rail associated with the braking, exit and accelerating sections of the intermediate station, viz., $I_{70}-I_{71}$, $I_{71}-I_{72}-I_{73}$, $I_{72}-I_{80}$, $I_{77}-I_{79}-I_{81}$, and $I_{80}-I_{81}-I_{82}$, receive current through their respective relays

R_{36} , R_{37} , R_{38} , R_{40} and R_{43} , not from the positive main direct, but from the positive main through the magnet 49. Hence, as long as there is a car on any one of these sections, the magnet 49 will be energized. Or, in other words, as long as either the exit section or any part of the entire block section belonging to the intermediate station is occupied, the switch points P_{10} , P_{11} , will be locked in the position in which they were last set.

It has been seen that when a block section is in the through position, before it can be set in the starting position it must pass through the braking position in order that the contactors K_{16} , K_{18} and K_{20} , Fig. 8, for example, may be set in the position to supply the starting voltage to the contactors K_{17} , K_{19} and K_{21} , respectively. If, therefore, with the controller C_6 in the starting position and the third block section in the through position, the switch points P_{10} , P_{11} , were thrown into the station position, the braking section would remain connected to full voltage, and any car arriving would do so at full speed, which would result in damage. To guard against this, I interlock the handles H_1 and H_2 of the control table, which operate the controller C_6 and the switch points P_{10} , P_{11} , respectively, so that it is impossible to throw these switch points into the station position without first setting the controller C_6 in the braking position. This is done by means of the cam C_{23} , which is mounted on the shaft S_{20} , which, it will be remembered, is worked through gearing by the handle H_2 . It will also be remembered that the cam C_{19} is mounted on a common shaft with the handle H_1 . In Fig. 51, the manner in which these two cams interlock will be apparent. As shown in the figure, H_2 is in the station position S and H_1 is free to assume either of its two alternative positions. But if H_2 be rocked in the counter-clockwise direction, the cam C_{23} will be turned in the clockwise direction and will lock the cam C_{19} in the position which it occupies in this figure, viz., the braking position B. Conversely, if the handle H_1 were set in the starting position A it would lock the handle H_2 against the station position S, so that before the switch points could be set in the station position it would be necessary to set the handle H_1 in the braking position B, as stated above.

When there is a car on the third block section, the second block section will, of course, be closed, and if this car passes off via the fourth block section the second block section will be opened in the normal manner. But if the car passes off the third block section by entering the intermediate station, this operation will not take place. Consequently it is necessary to provide means of

opening the second block section when the car enters the intermediate station.

This is done by means of the special relay R_{39} , Fig. 8. This relay is of the standard type, having a series solenoid S_{28} and a shunt solenoid S_{27} . The connection to the field conductor rail section $I_{73}-I_{74}$ is through the series solenoid S_{28} , and when a car passes into this section it causes contact to be made between the contacts W_s . One of the contacts W_s has a connection through the points 91 and 82 with the finger 45 of the controller C_6 , and the other contact W_s is connected through the point 89 to the conductor 64, which it will be remembered opens the second block section.

The operation, then is as follows:

When a car in entering the intermediate station passes the section $I_{73}-I_{74}$, it makes contact between the finger 45 and the conductor 62. But in starting the car upon the braking section the controller C_6 was necessarily set in the starting position. In this position the finger 45 is not energized and the second block section remains closed. But if the controller C_6 be then moved back to the braking position, the finger 45, which it will be remembered, is in the circuit for setting the contactors in the braking position, will be energized and with it the conductor 64, and the second block section will be opened.

The relay R_{39} is returned to its normal position by the next car arriving upon the section $I_{70}-I_{71}$, through connection between its shunt solenoid S_{27} and the conductor 62.

Referring now to Fig. 48, which is an elevational view of the control table seen from the left-hand, C_{30} is a cam carried upon the end of the shaft S_{13} , upon which the handle H_1 is also mounted. D_3 is a pawl pivoted at P_{13} , with a hooked end adapted to enter the notch N_3 of the cam C_{30} . W_3 is a weighted end which normally causes the hooked end of the pawl to press against the cam. The notch N_3 is in the position which permits the pawl to enter when the handle H_1 is in the braking position B. The in-closed magnet 90, comprising a solenoid and core upon which the rod S_{30} is mounted, when energized withdraws the pawl from engagement.

Returning to Fig. 8, magnet 90 may be found beneath the controller C_6 , and it will be seen that it has connection with the conductor 63, which is energized by the relay R_{37} whenever there is a car in the section $I_{71}-I_{72}-I_{73}$.

To recapitulate, therefore, when a car enters the intermediate station the block section ahead is not released until the braking section is reset in the braking position, and when so set it is locked in that position until the next car unlocks it. Thus, when the

switch points are in the station position it is impossible to have a car arrive on the braking section when it is in any position but the braking position.

In Fig. 5, the relay R_{23} performs a function similar to that of the relay R_{39} just described, i. e., it opens the block section ahead of the terminal station when the controller C_1 is in the braking position, the finger 28 of the controller C_1 supplying current to the contacts of the relay R_{23} only when the controller C_1 is in the braking position. The magnet 29 performs a function similar to that of the magnet 90, i. e., it unlocks the controller C_1 when there is a car on the section $I_{52}-I_{53}$.

Returning to Fig. 50:

S_{21} is a second countershaft extending in a direction parallel with the others and journaled at J_3 , J_2 , etc. It is geared to the shaft S_{15} through the gears G_6-G_8 , and is consequently operated by the handle H_3 . At the left end it carries the cam C_{26} , at the right end the cam C_{28} , and near its middle the cam C_{27} . It will be remembered, is the control handle for the approach section. In Fig. 51 it is shown in the reversing position R, and in the resulting position of the cam C_{26} it will be seen to lock the handle H_1 against the starting position A. This is to prevent the despatch of a car from the braking on to the approach section when the latter is set in the reversing position, for to do so would cause a burn-out of the motor. In any of the three remaining positions of the handle H_3 , however, there will be no interference with the handle H_1 .

Similarly, it will be found that if the handle H_3 be set in any other position but the reversing position which it occupies in Fig. 51, the handles H_5 and H_7 will be locked against the reversing position, though free to occupy any other position. This is to guard against reversing a car and sending it back from the siding or unloading section on to the approach section, as is frequently necessary in shunting, when the approach section is set in the starting or through position A or T respectively, for the same reasons as before. Conversely, it will be found that the handle H_3 is locked against the starting position A when either of the handles H_5 or H_7 is in the reversing position R.

The method of operation of the switch points P_{10} , P_{11} , etc., from a distance is as follows:

P_{14} , Figs. 46 and 49, is a pipe connecting to a reservoir filled with compressed air and communicating with the three-way cocks V_1 , V_2 , V_3 , and V_4 . The opposite connections of these cocks, viz. O_1 , O_2 , O_3 and O_4 are open to the atmosphere. In the position illustrated, therefore, the pipe P_{15} leading

from the valve V_1 will be in communication with the air reservoir, while the pipe P_{16} will be connected to the open orifice O_2 .

Referring now to Figs. 44 and 45:

5 P_{10} are the facing switch points of the intermediate stations. They are joined by the tie bar B_7 which has riveted to it near its middle the angle piece A_3 . Through a hole in A_3 passes the rod R_{46} , which has 10 mounted upon it the two pairs of locking nuts N_4 N_5 . Between these locking nuts and the angle A_3 are springs S_{31} and S_{32} , which are compressed between them and the angle A_3 .
15 The rod R_{46} is worked by the crank C_{31} , which is journaled at J_4 and actuated through the pinion G_9 and rack G_{10} by the piston of the air cylinder C_{32} .

The throw of the crank C_{31} is somewhat 20 greater than the motion of the switch points, so that in the position illustrated the spring S_{32} is in considerable compression while the spring S_{31} is free. In the opposite position the reverse would be the case.

25 The arc of motion of the crank C_{31} is 200 degrees, or 10 degrees past the dead center at each end of the stroke. Thus, the mechanism is self-locking, the pressure exerted by the spring in compression tending to prevent 30 the turning of the crank.

The air cylinder C_{32} is provided with the pipe connections O_5 and O_6 .

It is to be understood that the pipe P_{15} , Figs. 46 and 49, is connected to O_6 , Fig. 44, 35 and the pipe P_{16} to O_5 . The method of operation of the switch points P_{10} will now be obvious. The air cylinder of the switch points P_{11} is to be understood to be connected to branches of the pipes P_{15} and P_{16} 40 and operated simultaneously.

The handle H_4 , Fig. 50, works the three-way cocks V_3 and V_4 (through mechanism similar to that above described) which control the switch points P_{19} of the siding section 45.

In order that an operator at an intermediate station may know as each train approaches whether or not it is for his station, I provide an automatic means by which the 50 train itself conveys to him the desired information.

A_4 , Figs. 52 and 55, is an arm pivoted upon the bolt B_8 which passes through an extension E_1 upon the journal box J_5 of the 55 car. The arm A_4 carries at its outer end the roller R_{47} . G_{11} is a gear sector pivoted upon the same bolt B_8 and provided with a lug L_{66} , which engages a lug L_{67} upon the arm A_4 in such a way that while the gear G_{11} can 60 move the arm A_4 positively upward, it cannot move it positively in the reverse direction.

A_5 is a second arm carried upon the shaft S_{33} , which is journaled at J_6 . Upon the

shaft S_{33} is also fixed the gear G_{12} , which 65 meshes with the gear G_{11} .

R_{48} is a ratchet sector mounted upon one end of the rod R_{49} , which is journaled at J_7 and at its other end carries the gear G_{13} , which meshes with the gear G_{12} . D_4 is a pawl pivoted at P_{20} carrying at its outer end a roller that engages with the ratchet sector R_{48} .

S_{34} is a spring holding the pawl D_4 into 75 engagement with the ratchet sector R_{48} , and S_{35} is a spring attached to the hubs of both the arm A_4 and the arm A_5 .

It will be seen that there are five notches to the ratchet sector R_{48} and the corresponding positions of the arm A_5 are indicated by numbers painted upon the body of the car B_9 .

As the arm A_5 is lowered from one position to another successively, the gear G_{11} permits the arm A_4 to descend likewise under its own weight and the tension of the spring S_{35} . The stops S_{38} , S_{39} , engaging the pin P_{21} , limit the movement of the arm A_5 in each direction so that the roller R_{47} cannot descend lower than the position 96, while the ratchet and pawl hold the mechanism securely when it is set in any of the other positions 92, 93, 94 and 95. In any position but the uppermost the arm A_4 is free to rise against the tension of the spring S_{35} .

The points of attachment P_{22} and P_{23} of the spring S_{35} move simultaneously during the movement of the arms A_5 and A_4 in such a way that the distance between them remains approximately constant. Consequently the tension upon the spring S_{35} is the same for all positions.

In order that the mechanism may be set from either side of the car, a second arm A_6 , similar to the arm A_5 , is provided. It is carried upon the shaft S_{36} , which is journaled in the extension E_2 of the opposite journal box J_8 . The shaft S_{37} connects the shafts S_{33} and S_{36} through the universal joints U_1 , U_2 .

At a point a certain distance in advance of each intermediate station, a short section of conductor rail, which I call the "selective" rail, is mounted in insulators alongside the track in the path of the roller R_{47} .

When the roller makes contact with the selective rail, the fact is, in a manner to be explained hereinafter, indicated in the station, and it is this which informs the operator at the station that the car is intended to stop there.

In Figs. 56 and 57, one method of mounting the selective rail is shown. R_{50} is the selective rail.

It is carried by the insulators I_{106} which are mounted upon supports that are clamped directly to the flange of the track rail T_3 . These supports each comprise a clamp C_{33} and bolt B_{10} , which is screwed into it and

secured by the lock-nut N_6 so as to give a slight adjustment as to height. Each selective rail may be about thirty feet long and the ends are bent down as shown in Fig. 57 5 to avoid the damage to the roller that might result from striking a rough end.

The bolts B^{10} are of graduated lengths so that the selective rail may be set at four different heights, corresponding to the four 10 lower positions of the roller R_{47} .

At the first intermediate station the selective rail will be in the lowermost position where the roller will come in contact with it only in position 96, Fig. 56. At the next 15 station the selective rail is set in the next higher position, and so on, until at the fourth intermediate station it will be in the position shown in Fig. 56.

The bolt or support shown in Fig. 56 for 20 the selective rail is curved, and this curvature is only necessary at the fourth intermediate station for the purpose of allowing the support to clear the body of the passing car. At the other stations the bolts may be 25 straight, and the insulators I_{106} turned through an angle of 180° on the bolt.

On despatching a car the operator will set the roller in the position corresponding to the station at which he desires it to stop, 30 viz., 96 for the first station, 95 for the second, etc. When the roller is in the highest position, 92, it will pass all the intermediate stations.

The selective rail for the intermediate 35 station illustrated in Fig. 8 will be found at R_{50} , Fig. 7. It is connected through the conductor 65 to the shunt solenoid S_{25} of the special relay R_{41} and thence to the positive main. The arm A_4 not being insulated 40 from the car, which is, of course, in electrical contact with the track rail or negative main, when the roller touches the selective rail the circuit will be completed through the solenoid S_{25} , operating the relay and 45 making contact between the contacts W_7 . This will be found to complete a circuit from the positive main through the signal lamp L_{68} . The lamp L_{68} remains lighted until the car passes the insulator I_{73} , Fig. 8. This 50 is a double insulator, or, properly speaking, short section of conductor rail between two insulators, which I use in some places for more effective insulation, and the momentary flow of current to the motor field while 55 passing this section operates the relay R_{41} through the solenoid S_{26} and extinguishes the lamp L_{68} .

B_{22} , Fig. 8, is an electric bell that is operated in shunt with the lamp L_{14} to give 60 the operator audible notification of the arrival of a car on the braking section of the intermediate station. B_1 , Fig. 5, is an electric bell serving a similar purpose at the terminal station.

I do not wish to be understood as limiting 65 my invention to the form of system and apparatus herein disclosed, for it is evident that the principle of my invention may be practised with other arrangements and apparatus. 70

It is to be further understood that my invention is not limited to the employment 75 of a shunt wound motor except where so specified in the claims, for while a shunt wound motor is preferred, in some applications of my invention other types of motor may be employed.

Furthermore, it is to be understood that my invention is not to be limited to the employment 80 of electric light signals, but that any other form of visible or audible signal may be employed.

What I claim is:

1. In an electric railway system, a track section, a car, a motor thereon, conductors 85 extending along the trackway for energizing said motor, a second track section, means associated with said second track section automatically controlling said motor when said car is upon the first track section, and a controller for independently controlling said motor when said car is upon said first section, and for interrupting said automatic control of said first section by said means. 90

2. In an electric railway system, a track 95 section, a car, a motor thereon, conductors extending along the trackway for energizing said motor, a second track section, a relay through which said first track section is automatically controlled by said second track 100 section, and a controller for preventing control of said second track section through said relay and for independently controlling said motor when said car is upon said first track section. 105

3. In an electric railway system, a car, railway trackage on which said car travels, a motor on said car for driving the same, a contact conductor independent of said trackage, extending along the trackway for supplying current to the field of said motor, a second contact conductor independent of said trackage extending along said trackway for supplying current to the armature of said motor, a return contact conductor 110 comprised in said trackage common to the field and armature of said motor, permanent field and armature connections on said car, a source of current, and a controller for varying the connections between said source 115 of current and said contact conductors. 120

4. In an electric railway system, a car, a motor thereon for driving the same, a contact conductor extending along the trackway for supplying current to the field of 125 said motor, a second contact conductor extending along said trackway for supplying current to the armature of said motor, a re-

turn contact conductor common to the field and armature of said motor, a source of current, a resistance, and a controller for connecting the motor armature to said source of current through said resistance and the motor field directly to said source of current.

5. In an electric railway system, a car, a motor thereon for driving the same, a contact conductor extending along the trackway 10 for supplying current to the field of said motor, a second contact conductor extending along said trackway for supplying current to the armature of said motor, a return contact conductor common to said field and armature of said motor, a source of current, and a controller for connecting said source of current to the field of said motor and for isolating said armature from said source of current and closing a connection between 15 said armature contact conductor and said return contact conductor.

6. In an electric railway system, a car, a motor thereon for driving the same, a contact conductor extending along the trackway 25 for supplying current to the field of said motor, a second contact conductor extending along said trackway for supplying current to the armature of said motor, and a return contact conductor common to said field and armature of said motor, a source of current, and a controller for connecting said source of current to the field of said motor and for isolating said armature from said source of current and closing a connection between 30 said armature contact conductor and said return contact conductor through a resistance.

7. In an electric railway system, a car, a motor thereon for driving the same, a contact conductor extending along the trackway 40 for supplying current to the field of said motor, a second contact conductor extending along said trackway for supplying current to the armature of said motor, and a return contact conductor common to the field and armature of said motor, a source of current, a resistance, and a controller for connecting said motor field in shunt with said resistance.

50 8. In an electric railway system, a car, a motor thereon for driving the same, a contact conductor extending along the trackway for supplying current to the field of said motor, a second contact conductor extending along said trackway for supplying current to the armature of said motor, and a return contact conductor common to the field and armature of said motor, a source of current, a resistance, and a controller for connecting said motor field in shunt with said resistance and for reversing the current through said motor field.

9. In an electric railway system, a car, a railway trackage over which said car travels, 60 a shunt motor on said car for driving the

same; a contact conductor independent of said trackage extending along the trackway for supplying current to the shunt field of said motor; a second contact conductor independent of said trackage extending along 70 said trackway for supplying current to the armature of said motor, a return contact conductor comprised in said trackage common to said shunt field and armature of said motor, a source of current, and a controller for varying the connections between said source of current and said contact conductors.

10. In an electric railway system, a car, a shunt motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, a resistance, and a controller for connecting the motor armature to said source of current through said resistance and the motor field directly to said source of current.

11. In an electric railway system, a car, a shunt motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, and a controller for connecting said source of current to the field of said motor and for isolating said armature from said source of current and closing a connection between said armature contact conductor and said return contact conductor.

12. In an electric railway system, a car, a shunt motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, and a controller for connecting said source of current to the field of said motor and for isolating said armature from said source of current and closing a connection between said armature contact conductor and said return contact conductor through a resistance.

13. In an electric railway system, a car, a shunt motor thereon for driving the same, a contact conductor extending along the trackway for supplying current to the shunt field of said motor, a second contact conductor extending along said trackway for supplying current to the armature of said motor.

motor, a return contact conductor common to said shunt field and armature of said motor, a source of current, a resistance, and a controller for connecting said motor field in shunt with said resistance.

14. In an electric railway system, a car, a shunt motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, a resistance, and a controller for connecting said motor field in shunt with said resistance and for reversing the current through said motor field.

15. In an electric railway system, a car, a motor thereon for driving the same, shunt and series fields for said motor, a contact conductor extending along the path of travel of said car for supplying current to the shunt field of said motor, a second contact conductor extending along the path of travel of said car for supplying current to the armature and series field of said motor, a return contact conductor common to said shunt field and armature of said motor, and a controller external to said car and connections between said controller and said contact conductors for causing said shunt and series fields to operate cumulatively.

16. In an electric railway system, a car, a motor thereon for driving the same, shunt and series fields for said motor, a contact conductor extending along the path of travel of said car for supplying current to the shunt field of said motor, a second contact conductor extending along the path of travel of said car for supplying current to the armature and series field of said motor, a return contact conductor common to said shunt field and armature of said motor, and a controller external to said car and connections between said controller and said contact conductors for causing said shunt and series fields to operate differentially.

17. In an electric railway system, a car, a motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, a resistance, a controller for connecting the motor armature to said source of current through said resistance and the motor field directly to said source of current, and a field winding in series with said armature.

18. In an electric railway system, a car, a motor thereon for driving the same, a con-

tact conductor extending along the trackway for supplying current to the shunt field of said motor, a second contact conductor extending along said trackway for supplying current to the armature of said motor, a return contact conductor common to said shunt field and armature of said motor, a source of current, a controller for connecting said source of current to the field of said motor and for isolating said armature from said source of current and closing a connection between said armature contact conductor and said return contact conductor, and a field winding in series with said armature.

19. In an electric railway system, a car, a motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, a controller for connecting said source of current to said shunt field and for isolating said armature from said source of current and closing a connection between said armature and return contact conductors through a resistance, and a field winding in series with said armature.

20. In an electric railway system, a car, a motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, a resistance, a controller for connecting said motor field in shunt with said resistance, and a field winding in series with said armature.

21. In an electric railway system, a car, a motor thereon for driving the same, a contact conductor extending along the trackway for supplying current to the shunt field of said motor, a second contact conductor extending along said trackway for supplying current to the armature of said motor, a return contact conductor common to said shunt field and armature of said motor, a source of current, a resistance, a controller for connecting said motor field in shunt with said resistance and for reversing the current through said motor field, and a field winding in series with said armature.

22. In an electric railway system, a car, a shunt wound motor thereon for driving the same, a contact conductor extending along the trackway for supplying current to the shunt field of said motor, a second contact conductor extending along the trackway for supplying current to the armature of said motor, a return contact conductor com-

mon to said shunt field and armature of said motor, means sub-dividing said armature contact conductor, and a controller external to said car controlling connections to said field contact conductor and to a section of said armature contact conductor.

23. In an electric railway system, a car, a motor thereon, said motor having a shunt field winding, a contact conductor extending along the trackway for supplying current to said shunt motor field, a second contact conductor extending along the trackway for supplying current to the armature of said motor, return conducting means for said armature and field, a resistance, and means for connecting the shunt field of said motor in parallel with said resistance and in series with the motor armature.

24. In an electric railway system, a car, a motor thereon, said motor having a shunt field winding, a contact conductor extending along the trackway for supplying current to said shunt motor field, a second contact conductor extending along the trackway for supplying current to the armature of said motor, return conducting means for said armature and field, a resistance, and means for reversing the current through said shunt field of said motor and connecting the same in parallel with said resistance and in series with the motor armature.

25. In an electric railway system, a car, a motor thereon, a contact conductor extending along the trackway for normally supplying current to the field of said motor, a second contact conductor extending along the trackway for supplying current to the armature of said motor, a return contact conductor common to said field and armature of said motor, a source of current, a resistance, a controller at a station for connecting said armature contact conductor to one terminal of said source of current, and for connecting said return contact conductor to the other terminal of said source of current through said resistance, and for connecting said field contact conductor directly to said latter terminal of said source of current, whereby said field and the direction of rotation of said motor are reversed.

26. In an electric railway system, a car, a motor thereon, three contact conductors extending along the trackway and connecting respectively with one terminal of the field and one terminal of the armature of said motor and with the remaining terminals of both field and armature of said motor, a source of current, and a controller at a station for connecting said armature to the terminals of said source of current through a resistance and for connecting the field of said motor in parallel with said resistance.

27. In an electric railway system, the combination with a traveling car, of a shunt

wound motor thereon, conductors extending along the path of travel of said car communicating with the armature and field of said motor, a resistance external to said car, and means for connecting the shunt field of said motor in parallel with said resistance and in series with the armature of said motor.

28. In an electric railway system, the combination with a traveling car, of a shunt wound motor thereon, conductors extending along the path of travel of said car communicating with the armature and field of said motor, a resistance external to said car, and means for reversing the current through the shunt field of said motor and connecting the same in parallel with said resistance and in series with said armature.

29. In an electric railway system, a plurality of station sections each provided with insulated sections of independent armature and field contact conductors for supplying current to motors of railway cars, armature and field return conducting means, and a separate controller for each station section, whereby cars may be moved upon one section without disturbing those upon other sections.

30. In an electric railway system, an intermediate station, a block section including said intermediate station and braking and accelerating sections, a through track leading past said station, track switches and branch tracks leading into and out of said station, a controller at said station, and means for simultaneously operating said track switches and said controller, whereby said block section comes under the control of an operator at said station when said track switches are in a position to direct a car into said station, a succeeding block section, and means for transferring the control of said first block section to said succeeding block section when said track switches are set in position to direct a car past said station.

31. In an electric railway system, an intermediate station, a block section including said station, a track leading past said station, track switches and branch tracks leading into and out of said station, a controller at said station for controlling said block section, means for transferring the control of said block section to said controller when said track switches are set to direct a car into said station, a succeeding block section, and means for transferring the control of said first block section to said succeeding block section when said track switches are set to direct a car past said station, means for putting said first block section in condition to retard a car, means for putting said first block section into condition for allowing the passage of a car, and means controlled by said succeeding block section.

operative when said track switches are set to direct a car past said station for automatically setting said first block section in its said retarding or car passing positions according as there is or is not a car on said succeeding block section.

32. In an electric railway system, an intermediate station, a block section including said station, a track leading past said station, track switches and branch tracks leading into and out of said station, a controller at said station for controlling said block section, means for transferring the control of said block to said controller when said track switches are set to direct a car into said station, a succeeding block section, and means for transferring the control of said first block section to said succeeding block section when said track switches are set to direct a car past said station, means for putting said first block section in condition to retard a car, means for putting said first block section into condition for allowing the passage of a car, and a relay controlled by said succeeding block section operative when said track switches are set to direct a car past said station for automatically setting said first block section in its said retarding or car passing positions according as there is or is not a car on said succeeding block section.

33. In an electric railway system, an intermediate station, a track leading past said station, a track switch and a branch track leading into said station, a car braking section before said track switch, a controller for said braking section, a second controller for said track switch, and means for interlocking said controllers, whereby said track switch can be set in position to direct a car past said station only when said braking section is in condition for braking a car.

34. In an electric railway system, an intermediate station, a through track leading past said station, a track switch leading into said station to a branch track leading out of said station to said through track, a controller for despatching cars from said branch track to said through track, a second controller for operating said track switch, and means for interlocking said controllers, whereby cars can be despatched from said station only when said track switch is in position to direct a car into said station.

35. In an electric railway system, a plurality of adjacent sections, a controller for each section, and means for interlocking said controllers, whereby a car cannot be despatched from one section onto another section when said latter section is set in position to move a car in opposite direction.

36. In an electric railway system, the combination with a traveling car, of a shunt motor thereon, conductors extending along the path of travel of said car and communi-

cating with the armature and field of said motor, a resistance great with respect to the resistance of the armature of said motor, and means for connecting the field winding of said motor in parallel with said resistance and in series with said armature.

37. In an electric railway system, the combination with a traveling car, of a shunt motor thereon, conductors extending along the path of travel of said car and communicating with the armature and field of said motor, a resistance great with respect to the resistance of the armature of said motor, and means for reversing the current through the field winding of said motor and connecting said winding in parallel with said resistance and in series with said armature.

38. In an electric railway system, the combination with a traveling car, of a motor thereon having an armature and series and shunt fields, conductors extending along the path of travel of said car and communicating with said armature and fields, a resistance, and means for connecting said shunt field in parallel with said resistance and in series with said armature and said series field.

39. In an electric railway system, the combination with a traveling car, of a motor thereon having an armature and series and shunt fields, conductors extending along the path of travel of said car and communicating with said armature and fields, a resistance great with respect to the resistance of said armature, and means for connecting said shunt field in parallel with said resistance and in series with said armature and said series field.

40. In an electric railway system, the combination with a traveling car, of a motor thereon having an armature and series and shunt fields, conductors extending along the path of travel of said car and communicating with said armature and fields, a resistance, and means for reversing the connections of said shunt field and connecting the same in parallel with said resistance and in series with said armature and said series field.

41. In an electric railway system, the combination with a traveling car, of a motor thereon having an armature and series and shunt fields, conductors extending along the path of travel of said car and communicating with said armature and fields, a resistance great with respect to the resistance of said armature, and means for reversing the connections of said shunt field and connecting the same in parallel with said resistance and in series with said armature and said series field.

42. In an electric railway system, the combination with a traveling car, of a motor thereon having an armature and series and shunt fields normally operating in opposi-

tion to each other, conductors extending along the path of travel of said car and affording communication with said armature and fields, a resistance, and means for reversing the connections of said shunt field and connecting the same in series with said armature and said series field.

43. In an electric railway system, the combination with a traveling car, of a motor thereon having an armature and shunt and series fields normally opposing each other, conductors extending along the path of travel of said car and communicating with said armature and fields, a resistance great with respect to the resistance of said armature, and means for reversing the connections of said shunt field and connecting the same in parallel with said resistance and in series with said armature and said series field.

44. In an electric railway system, a car, a motor thereon, said motor having a shunt field winding, a contact conductor extending along the trackway for supplying current to said shunt field winding, a second contact conductor extending along the trackway for supplying current to the armature of said motor, return conducting means for said armature and field, a resistance external to said car, said resistance being great with respect to the resistance of the armature of said motor, and switching means external to said car coöperating with said contact conductors for connecting said shunt field winding in parallel with said resistance and in series with said motor armature.

45. In an electric railway system, a car, a motor thereon, said motor having a shunt field winding, a contact conductor extending along the trackway for supplying current to said shunt field winding, a second contact conductor extending along the trackway for supplying current to the armature of said motor, return conducting means for said armature and field, a resistance external to said car, said resistance being great with respect to the resistance of the armature of said motor, and means external to said car coöperating with said contact conductors for reversing the connections of said shunt field winding and connecting the same in parallel with said resistance and in series with said motor armature.

46. In an electric railway system, a car, a motor thereon, said motor having shunt and series field windings, independent contact conductors extending along the trackway for supplying current to said shunt field winding and to the armature of said motor respectively, return conducting means for said armature and field, a resistance external to said car, and switching means external to said car and coöperating with said contact conductors for connecting said shunt field

winding in parallel with said resistance and in series with said motor armature and said series field winding.

47. In an electric railway system, a car, a motor thereon, said motor having shunt and series field windings, independent contact conductors extending along the trackway for supplying current to said shunt field winding and to the armature of said motor respectively, return conducting means for said armature and field, a resistance external to said car, said resistance being great with respect to the resistance of said armature, and means external to said car coöperating with said contact conductors for connecting said shunt field winding in parallel with said resistance and in series with said motor armature and said series field winding.

48. In an electric railway system, a car, a motor thereon, said motor having shunt and series field windings, independent contact conductors extending along the trackway for supplying current to said shunt field winding and to the armature of said motor respectively, return conducting means for said armature and field, a resistance external to said car, and means external to said car coöperating with said contact conductors for reversing the connections of said shunt field winding and connecting the same in parallel with said resistance and in series with said motor armature and said series field winding.

49. In an electric railway system, a car, a motor thereon having an armature and series and shunt field winding normally opposing each other, independent contact conductors extending along the trackway for supplying current to said shunt field winding and to said motor armature respectively, a resistance, return conducting means for said armature and field, and means external to said car coöperating with said contact conductors for reversing the connections of said shunt field winding and connecting the same in parallel with said resistance and in series with said motor armature and said series field winding.

50. In an electric railway system, a car, a motor thereon having an armature and shunt and series field windings normally opposing each other, a source of current, independent contact conductors extending along the trackway and delivering current to said shunt field winding and said armature respectively, a return contact conductor common to said shunt field winding and said armature, and switching means external to said car and coöperating with said contact conductors for maintaining said shunt field winding excited from said source of current and connecting said armature and said series field winding between said armature contact conductor and return contact conductor, in-

dependently of said source of current, whereby said shunt and series field windings operate cumulatively and said car is electro-dynamically braked.

5 51. In an electric railway system, a car, a motor thereon having an armature and a field winding, independent contact conductors extending along the trackway and communicating respectively with a terminal of 10 said armature and a terminal of said field winding, a contact conductor common to said armature and field winding, said armature and field winding connections with said contact conductors being permanent on said 15 car, a controller external to said car co-operating with said contact conductors, a braking circuit and connections whereby said controller introduces said armature into said braking circuit while maintaining said 20 field winding separately excited.

52. In an electric railway system, a car, a motor thereon having an armature and a field winding, independent contact conductors extending along the trackway and communicating respectively with a terminal of 25 said armature and a terminal of said field winding, a contact conductor common to said armature and field winding, said armature and field winding connections with said 30 contact conductors being permanent on said car, a controller external to said car co-operating with said contact conductors, and connections whereby said controller causes 35 relative reversal of connections of said armature and field winding to reverse said motor.

53. In an electric railway system, a car, a motor thereon having an armature and a field winding, independent contact conductors extending along the trackway and communicating respectively with a terminal of 40 said armature and a terminal of said field winding, a contact conductor common to said armature and field winding, said armature and field winding connections with said 45 contact conductors being permanent on said car, a controller external to said car co-operating with said contact conductors, and connections whereby said controller in different positions causes said motor to reverse 50 and to electro-dynamically brake said car.

54. In an electric railway system, a car, a motor thereon having an armature and a field winding, independent contact conductors extending along the trackway and communicating respectively with a terminal of 55 said armature and a terminal of said field winding, a contact conductor common to said armature and field winding, said armature 60 and field winding connections with said contact conductors being permanent on said car, a controller external to said car co-operating with said contact conductors, a resistance, and connections whereby said controller in different positions introduces 65

said resistance into the armature circuit of said motor as a braking load and reverses the connections of said field winding and connects the same in parallel with said resistance to reverse said motor.

55. In an electric railway system, a car, a motor thereon having an armature and a field winding, independent contact conductors extending along the trackway and communicating respectively with a terminal of 70 said armature and a terminal of said field winding, a contact conductor common to said armature and field winding, said armature and field winding connections with said contact conductors being permanent on said 75 car, a controller external to said car co-operating with said contact conductors, a resistance, and connections whereby said controller introduces said resistance into the armature circuit of said motor for starting the same.

56. In an electric railway system, a car, a motor thereon having an armature and a field winding, independent contact conductors extending along the trackway and communicating respectively with a terminal of 80 said armature and a terminal of said field winding, a contact conductor common to said armature and field winding, said armature and field winding connections with said contact conductors being permanent on said 85 car, a controller external to said car co-operating with said contact conductors, a resistance, and connections whereby said controller introduces different amounts of said resistance into the 90 armature circuit of said motor for causing 95 said motor to run at different speeds.

57. In an electric railway system, a car, a motor thereon having an armature and a field winding, independent contact conductors extending along the trackway and communicating respectively with a terminal of 100 said armature and a terminal of said field winding, a contact conductor common to said armature and field winding, said armature and field winding connections with said contact conductors being permanent on said 105 car, a controller external to said car co-operating with said contact conductors, a resistance, and connections whereby said controller in different positions introduces different amounts of said resistance into the 110 armature circuit of said motor for causing said motor to run at different speeds.

58. In an electric railway system, a car, a motor thereon having an armature and a field winding, independent contact conductors extending along the trackway and communicating respectively with a terminal of 115 said armature and a terminal of said field winding, a contact conductor common to said armature and field winding, said armature and field winding connections with said contact conductors being permanent on said car, a controller external to said car co-operating with said contact conductors, and connections whereby said controller in different positions causes said motor to run in 120 different directions.

59. In an electric railway system, a car, a motor thereon having an armature and a field winding, independent contact conductors extending along the trackway and communicating respectively with a terminal of 125 said armature and a terminal of said field winding, a contact conductor common to said armature and field winding, said armature and field winding connections with said contact conductors being permanent on said car, a controller external to said car co-operating with said contact conductors, and connections whereby said controller in different positions introduces 130

ferent positions causes said motor to brake said car or move the same forward.

59. In an electric railway system, a car, a motor thereon having an armature and a field winding, independent contact conductors extending along the trackway and communicating respectively with a terminal of said armature and a terminal of said field winding, a contact conductor common to 10 said armature and field winding, said armature and field winding connections with said contact conductors being permanent on said car, a controller external to said car coöperating with said contact conductors, and connections whereby said controller in different 15 positions causes said motor to drive said car forward, reverse the same or brake the same.

60. In an electric railway system, a car, a 20 motor thereon having an armature and a field winding, independent contact conductors extending along the trackway and communicating respectively with a terminal of said armature and a terminal of said field 25 winding, a contact conductor common to said armature and field winding, said armature and field winding connections with said contact conductors being permanent on said car, a controller external to said car coöperating with said contact conductors, resistances external to said car, and connections whereby said controller in different 30 positions brings one of said resistances into the armature circuit for moving said car forward and for bringing another of said 35 resistances into said armature circuit in parallel with said field winding for reversing said car.

61. In an electric railway system, a car, 40 a motor thereon having an armature and a field winding, independent contact conductors extending along the trackway and communicating respectively with a terminal of said armature and a terminal of said field 45 winding, a contact conductor common to said armature and field winding, said armature and field winding connections with said contact conductors being permanent on said car, a controller external to said car coöperating with said contact conductors, resistances external to said car, and connections whereby said controller in different 50 positions introduces one of said resistances into the armature circuit to move said car forward and for bringing another of said resistances into said armature circuit for 55 braking said car.

62. In an electric railway system, a car, a 60 motor thereon having an armature and a field winding, independent contact conductors extending along the trackway and communicating respectively with a terminal of said armature and a terminal of said field winding, a contact conductor common to 65 said armature and field winding, said armature and field winding connections with said contact conductors being permanent on said car, a controller external to said car coöperating with said contact conductors, resistances external to said car, and connections whereby said controller in different positions causes said motor to move said car forward, reverse the same or brake the same, one of said resistances being brought into the armature circuit for moving said car forward and another of said resistances being brought into circuit for braking and reversing said car.

63. In an electric railway system, a car, a motor thereon for driving the same having an armature and a field winding, independent contact conductors extending along the trackway and communicating respectively with said armature and field windings, a common return conductor, a station, 80 said armature contact conductor and said return conductor sectionalized in advance of said station, and a controller external to said car having connections with said sectionalized armature and return conductors 85 for causing said motor to brake said car or to move said car forward.

64. In an electric railway system, a car, a motor thereon for driving the same having an armature and a field winding, independent contact conductors extending along the trackway and communicating respectively with said armature and field winding, a common return conductor, a station, means 90 dividing said armature contact and return conductors into sections in advance of said station, means subjecting one of said sections of armature contact conductor to reduced voltage for reducing the speed of said car, a succeeding section of said armature 95 contact conductor bringing said motor armature into a braking circuit through a section of said return conductor, and a controller external to said car having connections with said last named section of armature contact conductor for re-starting said car.

65. In an electric railway system, a car, a motor thereon for driving the same having an armature and a field winding, independent contact conductors extending along the trackway and communicating respectively with said armature and field winding, return conducting means for said armature and field, a station, a section of said armature contact conductor in advance of said station for bringing said motor armature into a braking circuit, a succeeding section of said armature contact conductor connecting said motor armature to a source of current of a voltage adapted to further retard said motor, a succeeding section of armature contact conductor adapted to bring said motor armature into a second braking circuit, and a controller external to said car 110

115

120

125

130

having connection with said last named section of armature conductor for supplying energy to said motor to move said car forward.

5 66. In an electric railway system, a car, a motor thereon for driving the same having an armature and a field winding, independent contact conductors extending along the trackway and communicating respectively with said armature and field winding, return conducting means for said armature and field, a station, approach sections of said armature and field contact conductors in advance of said station, and a controller external to said car and coöperating with said approach sections of armature and field contact conductors for moving said car toward said station at reduced speed, a braking section in advance of said approach section, and a second controller controlling said motor through said braking section for either braking said car or moving the same forward to said approach section.

10

15

20

10 to said approach section.

25 67. In an electric railway system, a car, a
motor thereon for driving the same having
an armature and a field winding, independ-
ent contact conductors extending along the
trackway and communicating respectively
with said armature and field winding, return
30 conducting means for said armature and
field, a station, approach sections of said
armature and field contact conductors in ad-
vance of said station, and a controller ex-
ternal to said car and coöperating with said
35 approach sections of armature and field con-
tact conductors for braking said car, a braking
section in advance of said approach sec-
tion, and a second controller controlling said
motor through said braking section for
40 either braking said car or moving the same
forward to said approach section

45 68. In an electric railway system, a car, a motor thereon for driving the same having an armature and a field winding, independent contact conductors extending along the trackway and communicating respectively with said armature and field winding, return conducting means for said armature and field, a station, approach sections of said 50 armature and field contact conductors in advance of said station, and a controller external to said car and coöperating with said approach sections of armature and field contact conductors for reversing said car, a 55 braking section in advance of said approach section, and a second controller controlling said motor through said braking section for either braking said car or moving the same forward to said approach section.

60 69. In an electric railway system, a car, a
motor thereon for driving the same having
an armature and a field winding, independ-
ent contact conductors extending along the
trackway and communicating respectively
65 with said armature and field winding, return

conducting means for said armature and field, a station, approach sections of said armature and field contact conductors in advance of said station, and a controller external to said car and coöperating with said approach sections of armature and field contact conductors for driving said car forward at reduced speed and braking said car, a braking section in advance of said approach section, and a second controller controlling said motor through said braking section for either braking said car or moving the same forward to said approach section.

70. In an electric railway system, a car, a motor thereon for driving the same having an armature and a field winding, independent contact conductors extending along the trackway and communicating respectively with said armature and field winding, return conducting means for said armature and field, a station, approach sections of said armature and field contact conductors in advance of said station, and a controller external to said car and coöperating with said approach sections of armature and field contact conductors for driving said car forward at reduced speed and reversing said car, a braking section in advance of said approach section, and a second controller controlling said motor through said braking section for either braking said car or moving the same forward to said approach section. 80 85 90 95

71. In an electric railway system, a car, a motor thereon for driving the same having an armature and a field winding, independent contact conductors extending along the trackway and communicating respectively with said armature and field winding, return conducting means for said armature and field, a station, approach sections of said armature and field contact conductors in advance of said station, and a controller external to said car and coöperating with said approach sections of armature and field contact conductors for driving said car forward at reduced speed, and reversing and braking said car, a braking section in advance of said approach section, and a second controller controlling said motor through said braking section for either braking said car or moving the same forward to said approach section. 100 105 110 115

72. In an electric railway system, a car, a motor thereon for driving the same having an armature and a field winding, independent contact conductors extending along the trackway and communicating respectively with said armature and field winding, return conducting means for said armature and field, means dividing said contact conductors into sections, neighboring lengths of said contact conductors independent of each other forming loading and unloading sections, a siding section, and a controller for each of said loading and unloading and siding sec- 130

tions adapted to control the car motor conductor connected to said return contact through the sectional contact conductors of conductor through progressively diminishing resistances, and a controller external to said sections.

73. In an electric railway system, a car, a motor thereon for driving the same, sectional contact conductors at or near a station, an automatic power block section beyond said station automatically controlling said motor, and a controller coöperating with said contact conductors at or near a station to control said motor and cause the same to deliver said car to said block section. 70

74. In an electric railway system, a car, a motor thereon for driving the same, contact conductors extending along the path of travel of said car and communicating with said motor, a power block section automatically controlling said motor through sectioned contact conductors, motor retarding sections intervening between said block section and a station, and a controller at a station controlling said motor after it has been retarded. 75

75. In an electric railway system, a car, a motor thereon for driving the same, a plurality of stations along the path of travel of said car, a power block section between neighboring stations comprising sectioned contact conductors communicating with said motor automatically controlling said motor, the automatic control of said motor terminating at or near said stations, sectional contact conductors at or near said stations, and controllers at said stations controlling said motor through said last named contact conductors. 80

76. In an electric railway system, a car, a shunt wound motor thereon for driving the same, a contact conductor extending along the trackway for supplying current to the shunt field of said motor, a second contact conductor extending along the trackway for normally supplying current to the armature of said motor, a return contact conductor 95

45 common to the shunt field and armature of said motor, means for sub-dividing said armature contact conductor; subdivisions of said armature contact conductor connected to said return contact conductor through paths of different resistances, and a controller external to said car closing said paths of different resistances in its different positions. 100

77. In an electric railway system, a car, a shunt wound motor thereon for driving the same, a contact conductor extending along the trackway for supplying current to the shunt field of said motor, a second contact conductor extending along said trackway for normally supplying current to the armature of said motor, a return contact conductor common to the shunt field and armature of said motor, means for sub-dividing said armature contact conductor, the subdivisions of said armature contact conductor connected to the other contact conductor, and a controller external to said car controlling connection of one of said two subdivisions of said contact conductor to another of said contact conductors. 115

81. In an electric railway system, a source of current, a car, a motor thereon for driving the same, contact conductors extending along the trackway and connected to the motor terminals; means for sub-dividing one of said contact conductors, two sub-divisions of said contact conductors connected to one terminal of said source of current whose other terminal is connected to the other contact conductor, and a controller external to said car controlling connection of one of said two subdivisions of said contact conductor to another of said contact conductors. 125

65 the subdivisions of said armature contact conductors connected to the other contact conductor, and a controller external to said car controlling connection of one of said two subdivisions of said contact conductors connected to one terminal of said source of current whose other terminal is connected to the other contact conductor, and a controller external to said car controlling connection of one of said two subdivisions of said contact conductor to another of said contact conductors. 130

5 of said contact conductor connected to another of said contact conductors, a third sub-division located between said two sub-divisions connected to one terminal of said 10 source of current whose other terminal is connected to the other contact conductor, and a controller external to said car controlling connection to another of said contact conductors of the one of said two sub-divisions of said contact conductor later traversed by said car.

15 82. In an electric railway system, a source of current, a car, a motor thereon, a contact conductor extending along the trackway for exciting the field of said motor, a second contact conductor extending along the trackway for normally supplying current to the armature of said motor, a return contact conductor common to said field and armature of 20 said motor, means for sub-dividing said armature contact conductor, two of said sub-divisions connected to said return contact conductor, a third sub-division of said armature contact conductor located between 25 said two sub-divisions and connected to said source of current, and a controller external to said car controlling connection of one of said two sub-divisions of said armature contact conductor to said return contact conductor.

30 83. In an electric railway system, a source of current, a car, a motor thereon, a contact conductor extending along the trackway for exciting the field of said motor, a second contact conductor extending along the trackway for normally supplying current to the armature of said motor, a return contact conductor common to said field and armature of 35 said motor, means for sub-dividing said armature contact conductor, two of said sub-divisions connected to said return contact conductor, a third sub-division of said armature contact conductor located between said two sub-divisions and connected to said 40 source of current, a controller external to said car controlling connection of one of said two sub-divisions of said armature contact conductor to said return contact conductor, and the other of said two sub-divisions 45 of armature contact conductor being first traversed by said car and permanently connected to said return contact conductor.

50 84. In an electric railway system, a source of current, a car, a motor thereon, a contact conductor extending along the trackway for supplying current to the field of said motor, a second contact conductor extending along the trackway for normally supplying current to the armature of said 55 motor, a return contact conductor, means for sub-dividing said armature contact conductor, resistances, two sub-divisions of said armature contact conductor connected through said resistances to said return contact conductor, a third sub-division of said 60

70 armature contact conductor located between said two sub-divisions and connected to said source of current, said resistances being of different values, and a controller external to said car controlling the connection of one of said two sub-divisions of armature contact conductor through said resistance of lesser value.

75 85. In an electric railway system, a car, a motor thereon, a sub-divided contact conductor extending along the trackway for supplying current to said motor, a return contact conductor, a contactor, a source of current, said contactor in one position connecting a sub-division of said contact conductor with said source of current and in another position connecting said sub-division of contact conductor with said return conductor, and a controller external to said car controlling said contactor.

80 86. In an electric railway system, a car, a motor thereon, a sub-divided contact conductor extending along the trackway for supplying current to said motor, a return contact conductor, a contactor, a source of current, said contactor in one position connecting a sub-division of said contact conductor with said source of current and in another position connecting said sub-division of contact conductor with said return conductor, and controllers external to said car connected in series with each other controlling said contactor.

85 87. In an electric railway system, a car, a motor thereon, a sub-divided contact conductor extending along the trackway for supplying current to said motor, a return contact conductor, a contactor, a source of current, said contactor in one position connecting a sub-division of said contact conductor with said source of current and in another position connecting said sub-division of contact conductor with said return conductor, means for throwing a track switch, and a controller operated with said last named means controlling said contactor.

90 88. In an electric railway system, a car, a motor thereon, a sub-divided contact conductor extending along the trackway for supplying current to said motor, a return contact conductor, a contactor, a source of current, said contactor in one position connecting a sub-division of said contact conductor with said source of current and in another position connecting said sub-division of contact conductor with said return conductor, means for throwing a track switch, controllers connected in series with each other controlling said contactor, one of said controllers operated with said track switch throwing means.

95 89. In an electric railway system, a car, a motor thereon for driving the same, a sub-divided contact conductor extending along 100

the trackway, a return contact conductor, a contactor, said contactor controlling a connection between a sub-division of said contact conductor and said return contact conductor, and a controller external to said car controlling said contactor.

90. In an electric railway system, a car, a motor thereon for driving the same, a sub-divided contact conductor extending along the trackway, a return contact conductor, a contactor, said contactor controlling a connection between a sub-division of said contact conductor and said return contact conductor, and a controller external to said car controlling said contactor, a track switch, means for actuating said track switch, said controller controlling said contactor to close said connection when said track switch is moved to position for movement of said car thereover.

91. In an electric railway system, a car, a motor thereon for driving the same, a sub-divided contact conductor extending along the path of travel of said car for supplying current to said motor, a source of current, a switch controlling connection between said source of current and a subdivision of said contact conductor, connections on said car permanently connecting said motor with said contact conductor, an electro-magnet controlling said switch, and a controller external to said car controlling said electro-magnet.

92. In an electric railway system, a car, a motor thereon for driving the same, a sub-divided contact conductor extending along the trackway for supplying current to said motor, a return conductor, a source of current, a contactor for connecting a subdivision of said contact conductor with said source of current, a controller external to said car controlling said contactor, a track switch, and means for actuating the same, said controller controlling said contactor to close said connection when said track switch is actuated for passage of a car there-through.

93. In an electric railway system, a station, a through track leading past said station, a branch track at said station leading therefrom to said through track, a track switch leading into said station to said branch track from said through track, a controller for despatching a car from said branch track to said through track, a second controller for operating said track switch, means for interlocking said controllers, whereby a car can be despatched from said station to said through track only when said track switch is in position to direct a car into said station, and means for locking said track switch in position preventing entry of a car into said station when a car has passed said switch on said through track.

94. In an electric railway system, a station, a through track leading past said station, a branch track at said station leading therefrom to said through track, a track switch leading into said station to said branch track from said through track, a controller for despatching a car from said branch track to said through track, a second controller for operating said track switch, means for interlocking said controllers, whereby a car can be despatched from said station to said through track only when said track switch is in position to direct a car into said station, and means for locking said track switch in position preventing entry of a car into said station when a car has passed said switch on said through track.

95. In an electric railway system, a station, a branch track thereat, a through track leading past said station, a track switch leading into said station to said branch track leading out of said station to said through track, and means for locking said track switch in position to prevent a car entering said station when a car has passed said switch on said through track.

96. In an electric railway system, a station, a branch track thereat, a through track leading past said station, a track switch leading into said station to said branch track leading out of said station to said through track, and means for locking said track switch in position to prevent a car entering said station when a car has passed said switch on said through track.

97. In an electric railway system, a station, a branch track thereat, a through track leading past said station, a track switch leading into said station to said branch track leading out of said station to said through track, means for locking said track switch in position to prevent a car entering said station when a car has passed said switch on said through track and maintaining said track switch so locked until said car has passed the junction of said branch and through tracks.

98. In an electric railway system, a station, a branch track thereat, a through track leading past said station, a track switch leading into said station to said branch track leading out of said station to said through track, means for locking said track

switch in position to prevent a car entering said station when a car has passed said switch on said through track and maintaining said track switch so locked until said car 5 has passed the junction of said branch and through tracks, a controller for despatching a car from said branch track to said through track, and means preventing actuation of said controller for despatching a car when 10 said track switch is in its said locked position.

99. In an electric railway system, a car, a motor thereon for driving the same, a block section having contact conductors communicating with said motor, said block section comprising braking and accelerating sections and including an intermediate station, a through track leading past said station, a branch track at said station, track 20 switches connecting said branch track with said through track, means for operating said track switches, and a controller operated simultaneously with said track switches, said controller having a position in which 25 it vests the control of said block section in an operator at said station when a track switch is in position to direct a car into said station, and in another position vests the control of said block section in the 30 succeeding block section when said track switch is in position to prevent entry of a car into said station.

100. In an electric railway system, a car, a motor thereon for driving the same, a block section having contact conductors communicating with said motor, said block section comprising braking and accelerating sections and including an intermediate station, a through track leading past said station, a branch track at said station, track 40 switches connecting said branch track with said through track, means for operating said track switches, a controller operated simultaneously with said track switches, 45 said controller having a position in which it vests the control of said block section in an operator at said station when a track switch is in position to direct a car into said station, and in another position vests the control of said block section in the succeeding block sections when said track switch is in position to prevent entry of a car into said station, and means controlled by said succeeding block sections for causing said 55 first named block section, when said track switch is thrown into the position preventing entry of a car into said station, to automatically assume the closed or open position in accordance with whether or not there is 60 a car on the succeeding block section.

101. In an electric railway system, a car, a motor thereon for driving the same, sectional contact conductors communicating with said motor, a station, means for bring-

ing said motor into a braking circuit 65 through a section of contact conductor before said station, means for normally locking said section in said braking connection, means responsive to the presence of a car upon said section for unlocking said means, 70 a block section preceding said braking section, and means operative only when said braking section is in braking condition for opening said block section.

102. In an electric railway system, a car, 75 a motor thereon for driving the same, a block section comprising sectional contact conductors in communication with said motor, an intermediate station included in said block section, a track leading past said 80 station, a track switch and a branch track leading into and out of said station, and means for locking said track switch in the position in which it was last set while there is a car on said block section or on said 85 branch track leading out of said station.

103. In an electric railway system, a car, a motor thereon for driving the same, an intermediate station, a through track leading past said station, a track switch and a 90 branch track leading into said station, contact conductors in advance of said track switch communicating with said motor, means for bringing said motor into a braking circuit through said contact conductors, a 95 controller in said braking circuit, a lock for said controller, and means unlocking said controller whereby said controller can be set in position permitting entry of a car into said station only when said motor is included in said braking circuit.

104. In an electric railway system, a car, a motor thereon for driving the same, a contact conductor extending along the path of travel of said car for supplying current 105 to the field of said motor, a second contact conductor extending along the path of travel of said car for supplying current to the armature of said motor, a return contact conductor common to said field and armature of said motor, means subdividing said armature and return contact conductors into sections, a source of current, resistances of different values, and a controller for connecting said source of current to said sections of armature and return contact conductors through said resistances.

105. In an electric railway system, a car, a motor thereon for driving the same, a contact conductor extending along the path 110 of travel of said car for supplying current to the field of said motor, a second contact conductor extending along the path of travel of said car for supplying current to the armature of said motor, a return conductor common to said field and armature of said motor, means subdividing said armature and return contact conductors

into sections, resistances of different values, and a controller external to said car for connecting the armature of said motor through said resistances through said sections of armature and return contact conductors.

106. In an electric railway system, a car, a motor thereon for driving the same, sectional contact conductors communicating with said motor, a station, means for bringing said motor into a braking circuit through a section of contact conductor at said station, means normally locking said section in the braking relation, and means responsive to the presence of a car upon said section for actuating said locking means to unlock said section.

107. In an electric railway system, a car, a motor thereon for driving the same, a station track, a through track leading around said station track, a track switch leading onto said station track, contact conductors communicating with said motor, a controller controlling said motor through said contact conductors and adapted to establish a braking circuit for said motor, means controlling said track switch, and means interlocking said controller and said track switch controlling means whereby said track switch can be set in position preventing entry of a car onto said station track only after said controller has been brought to motor braking position.

108. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, means interlocking said controller and said track switch controlling means whereby said track switch can be set in position preventing entry of a car into said station only after said controller has been brought to motor braking position, a block section including said contact conductors, and means responsive to the presence of said car in said block section for locking said track switch controlling means.

109. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, means interlocking said controller and said track switch controlling means whereby said track switch can be set

in position preventing entry of a car into said station only after said controller has been brought to motor braking position, a block section including said contact conductors, and means responsive to the presence of said car in said block section for locking said track switch controlling means in the position to which last moved.

110. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, a block section including said contact conductors, and means responsive to the presence of said car in said block section for locking said track switch controlling means.

111. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, a block section including said contact conductors, and means responsive to the presence of said car in said block section for locking said track switch controlling means in the position to which last moved.

112. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, means for locking said controller and means responsive to the presence of said motor in said braking circuit for unlocking said controller.

113. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, means for locking said controller, means responsive to the presence of said motor in said braking circuit for unlocking said controller, and means interlocking said controller and said track switch

controlling means whereby movement of said controller from its position in which it may be locked prevents said track switch from taking the position for directing a car past 5 said station.

114. In an electric railway system, a braking section before a station comprising means for braking a car, means locking said means in position for causing car braking, 10 means unlocking said first mentioned means when a car is upon said braking section, a block section preceding said braking section, and means operative only when said braking section is in condition to brake a car for setting said preceding block section in condition for passage of a car thereover.

115. In an electric railway system, a braking section before a station comprising means for braking a car, means locking said 20 means in position for causing car braking, means unlocking said first mentioned means when a car is upon said braking section, a block section preceding said braking section, and a relay operative only when said 25 braking section is in condition to brake a car for setting said preceding block section in condition for passage of a car thereover.

116. In an electric railway system, a block section, an intermediate station included in 30 said block section, a track leading past said station, track switches and branch tracks leading into and out of said station, and means responsive to the presence of a car on said block section or upon the track leading 35 out of said station for locking said track switches in the position in which they were last set.

117. In an electric railway system, a car, a motor thereon for driving the same, a 40 station, a through track leading past said station, a track switch and a branch track leading into said station, contact conductors communicating with said motor, a controller controlling said motor through said contact 45 conductors and adapted to establish a braking circuit for said motor, means controlling said track switch, a second controller operated with said track switch controlling means and coöperating with said first named 50 controller in establishing said braking circuit.

118. In an electric railway system, a car, a motor thereon for driving the same, a station, a through track leading past said station, a track switch and a branch track leading into said station, contact conductors communicating with said motor, a controller controlling said motor through said contact conductors and adapted to establish a braking circuit for said motor, means controlling said track switch, a second controller operated with said track switch controlling means and coöperating with said first named controller in establishing said braking cir-

cuit, said second controller when said track 65 switch is in position to direct a car past said station preventing establishment of said braking circuit by said first named controller.

119. In an electric railway system, a car, 70 a motor thereon for driving the same, a plurality of automatic block sections, a branch track, a track switch leading thereto, a controller associated with one of said block sections, and means controlled by said controller when said track switch is in position to direct a car past said branch track for closing said block section and opening the block section in the rear when a car is in the block section in advance. 80

120. In an electric railway system, a car, a motor thereon for driving the same, a plurality of automatic block sections, a branch track, a track switch leading thereto, a controller associated with one of said block sections, and means controlled by said controller when said track switch is in position to direct a car past said branch track for opening said block section when a car is on the second block in advance. 90

121. In an electric railway system, the combination with a car, of a motor thereon for driving the same, a through track, a branch track leading thereto, a controller associated with said branch track for controlling the movement of a car from said branch track to said through track, a track switch between said branch track and said through track, and means for locking said controller when said track switch is in position to direct a car past said branch track. 95

122. In an electric railway system, the combination with a car, of a motor thereon for driving the same, a through track, a branch track leading thereto, a controller associated with said branch track for controlling the movement of a car from said branch track to said through track, a track switch between said branch track and said through track, and means for locking said switch in position to direct a car from said branch track to said through track when said controller is in position for moving a car from said branch track to said through track. 105

123. In an electric railway system, a car, a shunt wound motor thereon for driving the same, a contact conductor extending along the trackway for supplying current to the shunt field of said motor, a second contact conductor extending along the trackway for supplying current to the armature of said motor, a return contact conductor common to said shunt field and armature of said motor, means sub-dividing said armature contact conductor, a source of current, resistances of different value through which the subdivisions of said armature contact

conductor connect with said source of current, and a controller external to said car controlling said motor.

124. In an electric railway system, a car, 5 a shunt wound motor thereon for driving the same, a contact conductor extending along the trackway for supplying current to the shunt field of said motor, a second contact conductor extending along said track- 10 way for supplying current to the armature of said motor, means sub-dividing said armature contact conductor, the subdivisions of said armature contact conductor subjected to different voltages, and a controller 15 external to said car controlling said motor.

125. In an electric railway system, a car, a motor thereon for driving the same, a contact conductor extending along the trackway for supplying current to said motor, 20 means sub-dividing said contact conductor, means for subjecting the successive sub-divisions of said contact conductor to progressively increasing voltages, whereby said car in passing over said sub-divisions is ac- 25celerated, a controller external to said car controlling said motor, the voltages impressed upon successive sub-divisions of said contact conductor and the lengths of said sub-divisions of said contact conductor being 30 so proportioned that the speed of the car at the initial ends of said successive sub-divisions is equal to the full speed of the car minus the speed of the car at the initial end of a sub-division divided by the full speed 35 of the car minus the speed of the car at the initial end of the next sub-division.

126. In an electric railway system, a car, a shunt wound motor thereon for driving the same, a contact conductor extending 40 along the trackway for supplying current to the shunt field of said motor, a second contact conductor extending along the trackway for normally supplying current to the armature of said motor, a return contact conductor common to the shunt field and armature of said motor, means for sub- 45 dividing said armature contact conductor, sub-divisions of said armature contact conductor connected to said return contact conductor through paths of different resistances, and a controller for said motor external to said car.

127. In an electric railway system, a source of current, a car, a motor thereon, a 55 contact conductor extending along the trackway for connecting the field of said motor to said source of current, whereby the motor field is excited to full strength, a second contact conductor extending along the 60 trackway for supplying current from said source to the armature of said motor, a return contact conductor common to said motor field and motor armature, means for sub-dividing said armature contact conduc-

tor, sub-divisions of said armature contact 65 conductor isolated from said source of current and connected to said return contact conductor through paths of different resistances, and a controller for said motor external to said car. 70

128. In an electric railway system, a car, a motor thereon, a pair of contact conductors extending along the trackway and connected with the terminals of the armature of said motor, means sub-dividing one of 75 said contact conductors, sub-divisions of said contact conductor connected to said other contact conductor through progressively diminishing resistances, a controller external to said car controlling said motor, whereby 80 the car in passing over said sub-divisions is retarded, said resistances and the lengths of said sub-divisions being so proportioned that the speeds of the car at the initial ends of successive subdivisions are equal to the speed 85 of the car at the initial end of any sub-division divided by the speed of the car at the initial end of the preceding subdivision.

129. In an electric railway system, a car, a motor thereon, a source of current, contact 90 conductors for supplying current from said source to said motor, a braking section before a station, and an approach section between said braking section and said station, a controller external to the car for controlling said motor when the car is on said approach section and means for subjecting a contact conductor of said approach section to such a reduced voltage as will insure a speed of said car suitable for entering said 100 station.

130. In an electric railway system, a plurality of track sections, track switches and branch tracks, a controller for said track switches and branch tracks, means for automatically controlling one of said sections from another of said sections, and means causing said automatic control to be interrupted by said controller when said track switches are set in the through position. 110

131. In an electric railway system, a plurality of track sections, electric means for controlling one of said sections, circuits for energizing said means, a relay controlling said circuits, means for automatically controlling said relay from another block section, a controller, and means coöperating with said controller for permitting control of said circuits through said controller in one position of the same independently of said relay and for establishing control through said relay in another position of said controller. 115

132. In an electric railway system, a track section, means for controlling said track section, circuits for energizing said means, a relay controlling said circuits, and a controller controlling said circuits independ- 125

ently of said relay when in one position and establishing control through said relay when in another position.

133. In an electric railway system, a plurality of track sections, a car, a motor thereon, conductors extending along the track-way for energizing said motor, means associated with one of said sections for controlling the movements of said car thereon, a controller controlling said means, and means including said controller for transferring control of said car to another of said sections.

134. In an electric railway system, a plu-

rality of track sections, a car, a motor thereon, conductors extending along the track-way for energizing said motor, means associated with one of said track sections for controlling the movements of said car thereon, means associated with another of said track sections for automatically controlling said first mentioned means, and a controller for interrupting the control of said car by said means associated with said other of said track sections.

In testimony whereof I have hereunto affixed my signature.

KENNETH E. STUART.

Copies of this patent may be obtained for five cents each, by addressing the "Commissioner of Patents, Washington, D. C."

It is hereby certified that in Letters Patent No. 1,240,897, granted September 25, 1917, upon the application of Kenneth E. Stuart, of Philadelphia, Pennsylvania, for an improvement in "Electric-Railway Systems," errors appear in the printed specification requiring correction as follows: Page 29, line 30, claim 99, for the word "section" read *sections*; page 30, line 112, claim 112, after the word "controller" insert a comma; page 32, line 97, claim 129, after the word "section" insert a comma; page 33, line 27, after the word "signature" insert the words *in the presence of the two subscribing witnesses*; same page, after the signature of the patentee insert the word *Witnesses*: followed by the names *James Whiting* and *S. C. Coles*; and that the said Letters Patent should be read with these corrections therein that the same may conform to the record of the case in the Patent Office.

Signed and sealed this 12th day of February, A. D., 1918.

[SEAL.]

J. T. NEWTON,

Commissioner of Patents.

Cl. 104—210.
